UNITED STATES PATENT OFFICE.

HUGH D. MACPHERSON, OF SUMMIT, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed December 22, 1920. Serial No. 432,571.

To all whom it may concern:

Be it known that I, HUGH DONALD MACPHERSON, a citizen of the United States, residing at Summit, in the county of Union, State of New Jersey, have invented certain new and useful Improvements in Telephone Systems, of which the following is a full, clear, concise, and exact description.

This invention relates to improvements in switching systems wherein methods and means are provided for controlling the transmission of current impulses for a plurality of trunk lines extending between widely separated offices, and has particular reference to such methods and means as applied to telephone systems.

In systems of this character, it has been proposed to employ, at opposite ends of a common signaling path, sending means for transmitting thereover, codes of current impulses, characteristic of the individual trunks and determined by the trunk line circuit which is temporarily associated with the common path for signaling purposes.

It is often desirable to extend a connection from an originating office to some distant office through one of a plurality of intermediate or tandem offices, by means of a sectionalized trunk line circuit, the sections thereof being interconnected at the various tandems offices.

An object of this invention is to selectively and automatically extend a connection from an originating office to terminate either at an adjacent office or at some distant office which may be reached only through the adjacent office, as well as to further extend the connection to another office located at a considerable distance which may be reached only through the adjacent and said distant offices. In either case, the selecting and operating current impulses are transmitted between the adjacent offices of the series over a common signaling path for the trunk lines interconnecting such offices.

It is also an object of the invention to establish connections between two offices by transmitting current impulses over a path common to a plurality of trunk circuits, which impulses control the selection of idle trunk circuits at an intervening office.

Another object is to control from one

point the building up of a repeater set at a distant point.

It is also an object of the invention to provide a system of this nature wherein the originating operator maintains complete control of the connection extending through a plurality of intermediate offices and in which the operators at the originating and terminating offices receive all of the supervisory signals while the through connections remain established.

A further object of the invention is to provide means whereby when a connection through intermediate offices requiring the use of amplifiers in the various sections thereof is selected, a properly balanced repeater is rendered effective and associated with each of the talking sections of the trunk circuit in response to the selecting impulses originating at the originating office.

In order to attain these objects, in accordance with one feature of the invention, there is provided at the originating office, a plurality of terminals for each trunk line circuit leading to an adjacent office, a plurality of terminals also being provided thereat for each of the trunk line circuits leading to offices adjacent thereto. The latter mentioned offices are also similarly equipped. Any of the terminals, when selected for use, causes the automatic association of the trunk with the common apparatus for transmitting codes of current impulses over the common signaling path leading to another office to selectively control apparatus thereat. The character of the codes of impulses are dependent upon the individual terminal of the trunk selected at the originating office and the apparatus which functions at the adjacent office will either cause the display of a signal thereat for connections terminating at such office or find an idle trunk circuit leading to another office and thereafter causes the association of such idle trunk with the common signaling path extending to the latter-mentioned office.

Another combination of impulses sent from this common path selects apparatus at the distant office which, as before, may function to cause the display of signals thereat or to further extend the connection to another office for its termination.

In accordance with another feature of the invention, the various sections of the trunk circuit being employed are temporarily associated with the common signaling paths joining the adjacent offices which are interconnected in this manner for the purpose of transmitting code impulses of current to control the supervisory signals associated with the originating and terminating ends of the sectionalized trunk circuit without producing any signals at the intermediate offices, such trunk circuits being rendered unavailable at the intermediate offices.

In accordance with a further feature of the invention, the apparatus at each intermediate office which selects the trunk leading to the next intermediate office or to the terminating office in response to the selecting impulses received over the common signaling path from the preceding intermediate or originating office, introduces a repeater set associated with such trunk circuit, between such trunk and the selected section of the trunk, as well as simultaneously connects the balancing network of the latter trunk with the repeater set.

These and other features of the invention not specifically mentioned above, will clearly appear from the following specification and accompanying drawings, Figs. 1 to 11 inclusive, of which when arranged in accordance with Figs. 13, 14 and 15, show an embodiment thereof in a telephone trunking system, and Fig. 12 shows in schematic form the arrangement in various offices of such a system.

It is believed the invention will be best understood from the following detailed description of the various operations.

40 The operator at office W extends a call to office X.

In extending this connection the figures are arranged as indicated in Fig. 13.

45 The operator at office W, desiring to establish a connection to the telephone line circuit, such as T, terminating at office X inserts the calling plug 1 of the toll cord circuit O into the jack 10 of the idle trunk line L1. A circuit is completed for relays 6 and 11 extending from battery through the winding of relay 6, sleeve contacts of plug 1 and jack 10, the winding and normal contact of relay 11, and the contact of relay 19 to ground. Relay 11 energizes in this circuit but relay 6, being marginal, does not operate at this time. Relays 12 and 13 also operate in response to the closure of the upper right-hand alternate contact of relay 11, and relay 19 operates due to the closure of the left-hand alternate contact of relay 11. The opening of the left-hand contact of relay 19 renders the various jacks of the trunk line L1 busy as will more fully appear in the description of similar relays at inter-

mediate offices and the opening of the contact of such relay removes the operating ground from the relays 21 and 31 associated with jacks 20 and 30. The relay 12, in operating, completes a ground connection to signal control conductor A10, the circuit therefor being traced from the outer left-hand alternate contact of relay 24, which operates over a circuit from battery at the outer right-hand alternate contact of relay 13 to ground at inner left-hand normal contact of relay 24 in response to the operation of relay 13, the left-hand normal contact of slow-release relay 25, the outer left-hand normal contact of relay 35, the outer right-hand alternate contact of relay 12 to the signal control conductor A10. Relay 24, in operating, locks over a circuit extending from battery through the outer right-hand alternate contact of relay 13, the winding and inner left-hand alternate contact of relay 24 and the lower outer right-hand alternate contact of relay 11 to ground. The closure of the inner right-hand alternate contact of relay 24 causes the operation of relay 34 over an obvious circuit, the latter relay also locking over an obvious circuit upon its operation. Relay 34, in operating, completes a ground connection for starting conductor X, which extends from ground through the outer right-hand alternate contact of relay 34, the outer right-hand alternate contact of relay 24, the right-hand contact of relay 25, the right-hand normal contact of relay 35 to starting conductor X. The connection of the ground to the common starting conductor X, causes the operation of start relay 200 which closes an operating circuit for motor magnet MM associated with the selector switch SS. The various brush arms of such selector switch advance step by step under the control of the motor magnet until the contact associated with the individual signaling conductor A10 is reached, whereupon, due to the previously traced ground connection for such conductor, relay 201 operates through its left-hand winding, the brush arm 202 and the individual conductor A10 to ground. The opening of the left-hand normal contact of relay 201 interrupts the circuit of motor magnet MM whereupon the switch arms of the selector switch SS stop in their attained position. Relay 201, in operating, locks through its right-hand winding and the contact of relay 203. As will be hereinafter described in detail the operation of relay 201 starts the operation of the distributor S, and at the beginning of the revolution of the brush arm 207 thereof, relay 205 operates. The control conductor B10 is then connected to battery through the brush arm 204 and the contacts of relays 203 and 205, so that a circuit is completed from battery through the con- 130

tacts of relays 203 and 205, the brush arm 204, the contact in engagement therewith, the control conductor B10, the inner right-hand contact of relay 12, the winding of relay 35, the right-hand contact of relay 25, the outer right-hand alternate contact of relay 24, and the outer right-hand alternate contact of relay 34 to ground. Relay 35 in operating locks over a circuit including its 5 right-hand contact and in opening its normal contacts, disconnects ground from the common start conductor X and the individual signal control conductor A10. Relay 201, in operating, also completes a circuit for the sending distributor release magnet SRM, which circuit extends from battery through the common ring 206, the brush arm 207, the segment 208, the outer right-hand alternate contact of relay 201 10 and the winding of release magnet SRM to ground. The attraction of the armature of the release magnet SRM, upon its energization, releases the brush arm 207 which is thereupon rotated through a complete cycle 15 at the end of which cycle the brush is stopped in its normal position, as shown. The brush arm 207, in being rotated, first engages the start segment 209, thereby connecting positive battery to the common signaling conductor P leading to the office X. The brush then moves out of engagement 20 with the segment 208, opening the energizing circuit of and causing the deenergization of release magnet SRM, which restores 25 its armature to the normal position for engagement with the arm 207, upon the completion of the cycle. With automatic selector switch SS in engagement with the first of the two contacts allotted to the jack 30 10 of the trunk line L1, it will be seen that positive current is connected with the first, second, fourth, fifth and sixth levels, while negative current is connected with the first contact of the third level only. When the brush arm 207 engages the segment 210, a 35 circuit is completed for relay 205, which extends from battery through the ring 206, brush arm 207, the segment 210, and the winding of relay 205 to ground. The 40 operation of relay 205, due to the formation of this circuit, removes the battery connected to brush arm 204 of the selector switch SS. As the brush arm 207 successively engages the individual sending segments 211 to 216, inclusive, of the distributor, impulses of current of the polarity connected with such segments through the brushes of the selector switch SS are successively connected with the common signaling 45 conductor P leading to office X. When the brush arm 207 moves out of engagement with the segment 210, the energizing circuit of slow release relay 205 is opened and when the brush arm thereafter engages segment 50 217, a circuit is formed to cause the energi-

zation of relay 203, which extends from battery through the ring 206, the brush arm 207, the segment 217 and the winding of relay 203 to ground. Release relay 203, in operating, opens the locking circuit of relay 201, and such relay releases. Relay 205 is made slow in releasing so that its normal contacts remain open until after the opening of the contact of relay 203. As the arm 207 disengages the segment 217, relay 203 55 is deenergized. When the brush arm 207 engages the restoring segment 218, negative current is connected with the signaling conductor P. The switch SS is now in position to be seized by another trunk line or 60 trunk line terminal, since the trunk line terminal of jack 10 is disconnected therefrom and the sending distributor is again in its normal position.

The connection of the positive current through the start segment 209 with the signaling conductor P, causes the operation of the differentially polarized relay 319, at office X over a circuit extending from positive battery, through the segment 209, the brush arm 207, the common sending ring 220, and the junction point between the windings of the differentially polarized relay 219, thence by one path through the lower winding of such relay and the artificial line associated therewith to ground, and by another path through the upper winding of relay 219, the conductor P, both windings of the differentially polarized relay 319, and the artificial line at the office 100 X to ground. The operation of relay 319, causes the operation of release magnet R'RM associated with the receiving distributor R' at office X. The circuit for such magnet may be traced from battery through the alternate contact of relay 319', the segment 320, the brush arm 321, the segment 322 and the winding of release magnet R'RM to ground. The attraction of the armature of the release magnet releases the brush arm 105 321, which is thereupon rotated through a complete cycle in synchronism with the sending distributor S at office W, at the end of which it is stopped in its normal position by the latch on the armature of the release magnet which has again assumed its 110 normal position. As the brush arm 321 moves out of engagement with the segments 320 and 322, the release magnet R'RM is deenergized thereby permitting the restoration of its armature to its normal position to arrest the motion of the brush arm 321 when it completes its rotation. When the brush arm engages the segment 323 a circuit is completed for relay 324, which extends from battery through the common ring 325, the brush arm 321, the segment 323, and the winding of relay 324 to ground. The closure of the contact of relay 324, prepares the locking circuits for the various relays 115 326 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935

to 381, associated with the receiving segments 311 to 316 of the distributor R'. The armature of the differentially polarized relay 319, remains in its alternate position 5 as long as positive current is connected with the other end of the common conductor P and is restored to its normal position whenever a negative current is connected with the other end of such conductor. The brush 10 arms 207 and 321 are being rotated at the same time and in synchronism with each other so that while the brush 207 is engaged with the individual sending segment 213, the armature of relay 319, is restored to its 15 normal position and brush 321 engages the individual receiving segment 313. A circuit is then completed which extends from battery through the normal contact of relay 319, the common receiving segment 333, 20 the brush 321, the individual receiving segment 313, and the lower winding of relay 328 to ground. The latter relay operates over this circuit and locks due to an obvious circuit, dependent upon the energization 25 of relay 324. The closure of the lower contact of relay 328 causes the operation of relays 334 and 335 over a circuit extending from battery through the windings of such 30 relays in series and the lower alternate contact of relay 328 to ground. When the brush arm 321 engages the segments 336 and 337, the signal-receiving relay associated with the trunk line L1 at office X, operates over 35 a circuit extending from negative battery through the lower normal contact of relay 331, the segment 336, the brush arm 321, the segment 337, the normal contact of relay 330, the lower normal contact of relay 338, the lower alternate contact of relay 335, the 40 upper normal contacts of relays 339 and 340, the signal-receiving conductor E, and the left-hand winding of signal-receiving relay 400 to ground. Relay 400 operates and locks through its right-hand winding, the polarity 45 of the current through the two windings of such relay being the same. The signal-receiving relay 401 also operates, since its right-hand winding is included in parallel with the left-hand winding of relay 400 by virtue 50 of the contact of slow-release relay 402. However, relay 401 does not lock due to the deenergized condition of slow-release relay 403. The energization of relay 401 does not at this time perform any useful 55 functions. The closure of the left-hand contact of relay 400 places the winding of supervisory relay 404 in bridge across the conductors of the trunk line L1, while the closure of the right-hand alternate contact of relay 400 causes the illumination of lamp 405 over a circuit extending from battery through the right-hand alternate contact of relay 400, the lower normal contact of relay 406, and the lamp 405 to ground. When 60 the brush 321 disengages segments 336 and 65 337, the energizing circuit of relays 400 and 401 is opened, causing the deenergization of relay 401. Slow-release relay 402 is then energized over a circuit extending from battery through the right-hand alternate contact of relay 400, the lower normal contact of relay 406, and the winding of slow-release relay 402 to ground. Slow release relay 403 is also energized by the release of relay 401. When the brush arm 321 engages the segments 320 and 322, the armature of relay 319 is in its normal position since the brush arm 207 is connected with the restoring segment 218. Negative current is, therefore, 70 connected with the common signaling path or conductor P, so that the energizing circuit of release magnet R'RM is opened. The engagement of the brush 321 with the segment 341 causes the release of relay 324 so that the locking circuit of relay 328 is 75 opened and relays 334 and 335 are deenergized. All apparatus associated with the 80 automatic selecting switch SS, the sending distributor S, the receiving distributor R' and the receiving circuit at office X, is now 85 in normal condition so that it may be employed in connection with any other trunk line circuit. The lighting of the lamp 405 serves as a guard signal to the operator at 90 the terminating position of office X, indicating that the operator at the originating office W has connected the toll cord circuit O with the trunk line circuit L1. 95

Connection of toll switching trunk circuit Q with the telephone line circuit T terminating at office X.

The operator at office X may now connect her head set indicated at O.T. to the line L1 and secure from the operator at office W 105 the desired number. She may also communicate with the toll switching trunk operator at office X, before whom the telephone line circuit T terminates over an order wire (not shown), to secure an assignment of a 110 toll switching trunk. The toll switching operator at the office X informs the incoming or receiving operator at the same office that the toll switching trunk Q, leading between such positions of the office X, should 115 be employed for extending the connection to the wanted line circuit T. Immediately upon assigning the trunk Q for this purpose, the toll switching operator inserts the plug 500 of the toll switching trunk Q into the jack 501 of the desired line circuit T. The cut-off relay 502 of the line circuit and the sleeve relay 503 of the toll switching trunk Q thereupon operate over an obvious 120 circuit. The operation of relay 502 performs its usual function in removing the line relay 504 from its association with the line conductors and thereby prevents the display of the usual line signal lamp 505 upon 125 the answer of the called party. The open- 130

ing of the right-hand normal contact of relay 503 disconnects the usual operator's telephone circuit testing arrangement from the tip conductor of the cord circuit with which a test is made, by placing such tip conductor in contact with the sleeve of jack 501 prior to the insertion of the plug 500. The closure of the right-hand alternate contact of relay 503 completes the continuity of the tip conductor of the trunk circuit, while the closure of the left-hand alternate contact of such relay causes the illumination of lamp 506 over a circuit extending from battery through the lamp 506, the left-hand alternate contact of relay 503, the resistance 507, and the normal contact of relay 508 to ground.

Connection of the trunk line circuit L1 with the toll switching trunk circuit Q.

The operator at office X, upon observing the lighted condition of the lamp 405, inserts the plug 407 of the trunk line L1 into the jack 509 of the toll switching trunk Q. Relay 408 thereupon operates over an obvious circuit. The operation of relay 408 causes the operation of relay 406 over an obvious circuit, the opening of the lower normal contact of relay 406 extinguishing the lamp 405 and releasing slow release relay 402. The opening of the upper normal contact of relay 406 disconnects the usual operator's telephone testing set from the trunk line L1 and the closure of the upper alternate contact of such relay completes the continuity of the tip conductor of the trunk line L1.

The supervisory relay 404 of the trunk line L1 and relay 508 of the toll switching trunk Q, operate over a circuit extending from battery through the left-hand winding of relay 508, the left-hand normal contact of relay 510, the ring contacts of jack 509 and plug 407, the lower normal contact of relay 409, the lower normal contact of relay 410, the left-hand alternate contact of relay 400, the winding of relay 404, the upper normal contacts of relays 410 and 409 in series, the upper alternate contact of relay 406, the tip contacts of plug 407 and jack 509, the right-hand normal contact of relay 510, and the right-hand winding of relay 508 to ground. The energization of relay 508 extinguishes the lamp 506 at the toll switching trunk position. The energization of supervisory relay 404 causes the operation of slow-to-operate and release relays 411 and 412 and relay 413, the energizing circuit for relay 411 extending from battery through the winding of relay 411, the alternate contact of supervisory relay 404, and the normal contact of marginal relay 414 to ground. Relay 412 operates over a circuit extending from battery, through the

winding and right-hand normal contact of 65 said relay, the right-hand contact of relay 415, the outer right-hand normal contact of relay 416, the alternate contact of the supervisory relay 404 and the normal contact of relay 414 to ground. Inasmuch as the relay 412 is slow to operate, a circuit will be established for relay 413 before the armatures of relay 412 are attracted, which circuit is traceable from ground, through the 70 normal contact of relay 414, the alternate contact of relay 404, the outer right-hand normal contact of relay 416, the right-hand contact of relay 415, the left-hand normal contact of relay 412, the inner right-hand normal contact and winding of relay 413, 75 the inner left-hand contact of relay 415, the start conductor X' and the winding of start relay 341 of the sending distributor S' to grounded battery. Relay 413 energizes and locks through its make-before-break contact 80 and, in so doing, disconnects the ground at the marginal relay 414 from the common start conductor X'. However, the ground on this conductor is now maintained through the locking circuit for relay 413. Relay 412 85 is locked over a circuit traceable from battery through the winding and right-hand alternate contact of said relay, the left hand normal contact of relay 417, the outer right hand normal contact of relay 416, the alternate contact of relay 404 and the normal contact of relay 414 to ground. The individual signal control conductor A'10 is grounded by the closure of the outer left-hand alternate contact of relay 413. The 90 energization of relay 413 causes the operation of relay 418 over a circuit extending from battery through the right hand alternate contact of relay 400, the right hand normal contact of relay 419, the winding 95 of relay 418, the left hand normal contact of relay 420 and the inner left hand alternate contact of relay 413 to ground. The operation of relay 418 closes a circuit for 100 relay 420, but this relay is shunted through contacts of relays 413 and 416. Upon the grounding of the common start conductor X' as previously described, the sending apparatus at office X functions to transmit a 105 combination of current impulses over the common signaling path P to the office W, which is similar, in character to that transmitted from the office W to the office X in connection with the lighting of the guard lamp at the office X. The common start relay 341 operates in response to the grounding of the start conductor X' and a circuit for motor magnet MM' is completed. The motor magnet MM' is of the ordinary self-interrupting type and advances the various 110 brush arms of the selector switch SS' until the brush arm 342 engages the conductor A'10, which has been grounded by the 115

120 motor magnet MM'. The motor magnet MM' advances the selector switch SS' until the brush arm 342 engages the conductor A'10, which has been grounded by the 125

above-mentioned operations of the relays. Upon engaging such conductor relay 343 operates to discontinue the operation of the motor magnet and the associated brush arms, the relay 343 locking over an obvious circuit including the contact of relay 344. When the brush arm 342 engages the conductor A'10, the brush arm 345 is in engagement with the release conductor B'10 so that upon the operation of relay 346 after the distributor S' has started its revolution, current flows over conductor B'10 from the normal contact of relay 344 through the alternate contact of relay 346, brush arm 345, the conductor B'10 and the winding of relay 415 to ground. The operation of relay 415 removes the ground connection from the common start conductor X' and causes the release of relay 413 and consequent removal of ground from the individual signaling conductor A'10. In releasing, relay 413 removes the shunt from around relay 420 whereupon the latter relay operates over a circuit through the contact of relay 418 to ground at the inner right hand normal contact of relay 416. When the relay 343 operates, the release magnet S'RM energizes to release the brush arm 353 which then makes a complete revolution. During this revolution, the brush arm 353 successively engages segments 347 to 352 and a series of current impulses is thereby transmitted over the common signaling path P in accordance with the polarities connected to said segments through the brush arms of the selector SS'. The sending distributor S', during the completion of the cycle of the brush arm 353, functions in exactly the same manner as the sending distributor S at the office W, which has been described in the transmission of the signal to light the guard lamp at the office X. Therefore, the impulses of current which are arranged in the same manner as previously described, are transmitted over the common signaling conductor P to the office W, and are received thereat by the differentially polarized relay 219. The receiving distributor R functions in the same manner as distributor R', as previously described, to selectively operate certain relays and thereby select the signal-receiving conductor E' and to send thereover an impulse of negative polarity. As the brush arm 221 rotates, relay 222 is first energized and then as the segments 223 to 228 are engaged, circuits are prepared for each of the relays 229 to 234. However, only relay 231 operates and locks under the control of relay 222. Relay 231 operates relays 235 and 236. When the brush arm 221 engages segments 237 and 238, a circuit is established from negative battery through the lower normal contact of relay 234, the segments 237 and 238, the lower normal con-

tacts of relays 233 and 239, the lower alternate contact of relay 236 and the upper normal contacts of relays 240 and 241 to the conductor E'.

The current of negative polarity traversing the signal-receiving conductor E', flows through the left-hand winding of the signal-receiving relay 27, causing the operation of such relay. Relay 29 does not operate due to the energization of relay 28 which operated when relay 13 was energized. Relay 27 locks since the polarities of the currents flowing through the energizing and locking windings thereof are such that the relay is maintained energized. The energization of relay 27 releases relay 28 but this relay does not close its contact until after the impulse has been transmitted over conductor E'. The resistance 26 is connected in a branch circuit around the winding of relay 11, the branch circuit being traceable from ground through the normal contact of relay 29, the left-hand alternate contact of relay 27, the resistance 26, the inner right-hand contact of relay 13, to the sleeve contact of jack 10. By the introduction of this branch circuit, the amount of current flowing through the winding of marginal supervisory relay 6 is increased sufficiently to cause the operation of such relay and to cause the subsequent lighting of the supervisory lamp 7 over an obvious circuit. As soon as the set of impulses is transmitted from the office X to the office W and received thereat, all the apparatus employed in the sending of such impulses is restored to its normal condition in a manner similar to that described in connection with the impulses transmitted in response to the insertion of the plug 1 into the jack 10. It will be borne in mind that relays 418 and 420 remain energized since relay 400 is still locked.

The operator at office W actuates the ringing key.

The operator at office W, observing the lighted condition of the supervisory lamp 7, is advised thereby that the connection has been established with the telephone line circuit T at the office X. The ringing key 2 is then actuated, which completes a circuit from the source of ringing current through the lower alternate contact of key 2, the ring contacts of plug 1 and jack 10, the lower normal contact of relay 16, the condenser 18, the winding of ringing response relay 17, the upper normal contact of relay 16, the tip contacts of jack 10 and plug 1 and the upper alternate contact of key 2 to ground. The ringing of current flowing over this path causes the operation of relay 17, which also causes the operation of slow-release relay 25 over an obvious circuit. Relays 17

and 25 are maintained operated while the ringing current is flowing over the circuit, but release when such current flow is discontinued. Relay 25, in operating, opens 5 the locking circuit of and thereby permits the release of relay 35.

The operator at office W releases the ringing key.

10 Upon the restoration of the ringing key 2 of the operator's cord circuit O to its normal position, relay 17 releases, causing the deenergization of relay 25. A ground connection is thus completed for the common 15 start conductor X, which extends from the outer right-hand alternate contact of relay 34, through the outer right-hand alternate contact of relay 24, the right-hand normal contact of relay 25, the inner left-hand contact of relay 35, to the start conductor X. A ground connection is also completed for the individual signal-control conductor A10, which extends from ground through the outer left-hand alternate contact of relay 24, 20 the left-hand normal contact of relay 25, the outer left-hand normal contact of relay 35, the outer right-hand alternate contact of relay 12, to the individual signal-control conductor A10. The grounding of these two 25 conductors, causes the operation of the sending distributor S and the associated selector switch SS to function to send over the common signaling path P from the office W to the office X, a combination of impulses similar 30 to that transmitted in response to the connection of the cord circuit O with the jack 10. These impulses are received by the common receiving apparatus including the receiving distributor R' and the various associated locking and selecting relays, and, 35 therefore, select the signal-receiving conductor E as in the previous case, and thereupon an impulse of negative polarity of current is transmitted over such conductor. 40 This impulse of current being of the same polarity as that which originally flowed through the left-hand winding of relay 400, produces no effect on such relay. However, due to the deenergized condition of relay 402, such current also flows through the 45 right-hand winding of relay 401 and causes its energization. Relay 403 which was maintained in an energized condition over a circuit extending from battery through the 50 right-hand alternate contact of relay 400 and the normal contact of relay 401, deenergizes upon the energization of relay 401, but due to the fact that relay 403 is slow to release, a temporary locking circuit is provided for relay 401 which includes the left-hand winding and left-hand alternate contact of relay 401 and the alternate contact of relay 403 to ground. While relay 401 is operated, a circuit is formed from battery through the right-hand alternate contact of 55

relay 400, the right hand alternate contact of relay 401 and the winding of slow-release relay 421 to ground. Relay 421, in operating, closes an obvious circuit for slow relay 422. While relay 421 is operated a circuit is 60 completed for ringing relay 410, which extends from battery through the winding of relay 410 and the right-hand alternate contact of relay 421 to ground. Due to the slow release nature of relay 421, as well as 65 relay 403, relay 410 is maintained operated for an appreciable time after the release of the ringing key at the office W. During such period a circuit is completed from the source of ringing current through the lower alternate contact of relay 410, the lower normal contact of relay 409, the ring contacts of plug 407 and jack 509, the winding of ringing response relay 511, the tip contacts of jack 509 and plug 407, the upper alternate contact of 70 relay 406, the upper normal contact of relay 409, and the upper alternate contact of relay 410 to ground. Ringing relay 512 thereupon operates over a circuit extending 75 from battery through the left-hand winding of relay 510, the winding of relay 512 and the contact of relay 511 to ground. Relay 512, in operating, completes a circuit for the ringing current which extends from the source of such current through the right-hand alternate contact of relay 512, the ring contacts of plug 500 and jack 501, the winding of the signaling bell at the station on the line circuit T, the tip contacts of jack 501 and plug 500, the right-hand alternate contact of relay 503 and the left-hand alternate contact of relay 512 to ground. The bell at the subscriber's station is thereby operated to signal subscriber that a call awaits an answer. As soon as the slow release relay 80 421 is entirely deenergized, relay 410 releases and removes the current from the trunk line circuit L1 and the connected toll switching trunk Q so that relays 511 and 512 release and remove the ringing current from 85 the telephone line circuit T. Thus upon each actuation of the ringing key, the following release of such key transmits a combination of impulses of current to the office X and causes the functioning of apparatus 90 thereat to apply ringing current through the toll switching trunk Q to the selected line circuit T for an appreciable predetermined interval.

The subscriber at the station on the telephone line circuit T removes the receiver from the switchhook.

The subscriber at the station on the line circuit T, terminating at the office X, in response to the signaling bell at such station, removes the receiver from the switchhook, causing the operation of supervisory relay 513 over a circuit extending from battery 125 through the winding of relay 513, the right- 130

hand normal contact of relay 512, the ring contacts of plug 500 and jack 501, the telephone apparatus at the station on the line circuit T, the tip contacts of jack 501 and plug 500, the right-hand alternate contact of relay 503 and the left-hand normal contact of relay 512 to ground. Relay 513, in operating, causes the energization of relay 510 over a circuit extending from battery 10 through the left-hand winding of relay 510, the contact of supervisory relay 513, the right-hand winding of relay 510 and the alternate contact of relay 508 to ground. By the operation of relay 510, relay 508 is 15 disconnected from the circuit including the supervisory relay 404 of the trunk line L1. However, relay 508 remains in operated condition due to the circuit which may be traced from battery through the left-hand winding of relay 508 and the alternate contact of relay 510 to ground. Relay 510, in operating, also causes the deenergization of the supervisory relay 404 due to 20 the opening of the circuit thereof by disconnecting the windings of relay 508 from trunk L1. Relay 404, in releasing opens the circuit of relay 411 but this relay is very slow to release and therefore does not immediately open its alternate contact. A circuit is therefore established for the slow 25 to release relay 423 extending from battery through the winding of said relay, the alternate contact of relay 411, the normal contact of relay 404 and the normal contact of relay 414 to ground. The release of relay 404 also opens the locking circuit for relay 412 which is slightly slow in releasing, said circuit extending through the outer right hand normal contact of relay 416. 30 When relay 411 is completely released, a circuit is established for relay 416 which extends from battery on the start conductor X' through the outer left hand contact of relay 415, the winding of relay 416, the outer right hand normal contact of relay 413, the right-hand contact of relay 420 and the normal contacts of relays 411, 404 and 414. Relay 416 energizes and locks through 35 its right hand alternate contact. The removal of ground from the inner right hand normal contact of relay 416 causes the release of relays 418 and 420. Relay 416, in closing its left-hand contact, grounds the individual signal control conductor C'10, 40 while the common start conductor X' is grounded through the outer left-hand contact of relay 415, the winding and right-hand alternate contact of relay 416. The grounding of the start conductor X', as in 45 the previous instance described in connection with the completion of the transmission circuit, causes the operation of the common start relay 341 at the office X and the remainder of the common sending apparatus thereat to function in a manner similar

to that described in the previous instance. However, the motor magnet MM' continues in its operation until the brush arm 342 engages the grounded signal-control conductor C'10, which is connected to the second of the contacts on the bank associated with the brush arm 342 which are allotted to the terminal or jack 10 of the trunk line L1. In this instance, when the brush arm 353 engages segments 349 and 352 impulses of negative polarity are sent by the sending distributor S' and these impulses are received by the differentially polarized relay 219 and the receiving distributor R at the office W in the manner described, to select the signal receiving conductor E' at the latter office. Relays 231 and 234 are operated by the negative impulses transmitted in a manner that will be understood from previous description so that the impulse of current which flows over the signaling conductor E' at the office W is of positive polarity, and due to the arrangement of the windings on the signal-receiving relay 27, current of this polarity differentiates and causes said relay to release. Although the current flows through the left-hand winding of relay 29, no material effect is produced thereby. Upon the release of relay 27, relay 28 is again energized to disconnect the signal-receiving conductor E' from the left-hand winding of relay 29 and the resistance 26 is removed from its parallel relation with the winding of relay 11, whereupon marginal relay 6 releases and extinguishes the supervisory lamp 7 to inform the operator that the desired subscriber has responded to the call.

Upon the sending of the impulses over the common signaling path P, all sending and receiving apparatus associated with the transmission of such impulses restores to normal, as previously described. The connection of battery through arm 345 to the conductor B'10 at the station X after impulses have been transmitted, causes the operation of relay 415 to restore the relays at such office to normal which have been used in starting the transmission of the impulses. The connection is thus established between the cord circuit Q to which a regular telephone circuit of any particular type may be connected in the usual well-known manner (not shown), and the station on the line circuit T terminating at the office X, such connection including the trunk line L1 and the toll switching trunk circuit Q.

The subscriber restores the receiver to the switchhook.

At the conclusion of the conversation the subscriber at the station on the line circuit T restores the receiver to the switchhook, releasing supervisory relay 513 of the trunk

circuit Q, which relay, in releasing, opens the circuit of relay 510. Relay 508 is thereupon connected in circuit with the supervisory relay 404 of the trunk line L1 to cause the energization of the latter relay. The energization of supervisory relay 404 causes the energization of the relays as mentioned in connection with the establishment of the connection between the trunk line L1 and the toll switching trunk Q. Such operations also ground the signal control conductor A'10 and the common start conductor X'. In response to the grounding of these conductors, the common sending apparatus at office X functions in exactly the same manner as previously described, to send the combination of impulses over the common signaling path P to the office W, where such impulses are received to cause the selection of the signal-receiving conductor E' and to transmit thereover an impulse of negative polarity. This impulse of current causes the operation of relay 27, flowing through its left-hand winding, such relay immediately locking through its right-hand winding. The resistance 26 is again placed in parallel relation with the winding of relay 11 to cause sufficient current to flow through the branch including the winding of marginal supervisory relay 6, thereby illuminating the lamp 7 over an obvious circuit. As in the previous instance, upon the transmission of these impulses all of the individual and common sending apparatus and the common receiving apparatus is restored to normal.

The operator at office W disconnects the toll cord circuit O from the trunk line circuit L1.

The operator at office W, upon observing the lighted condition of the supervisory lamp 7, withdraws the plug 1 from the jack 10, causing the release of relays 6 and 11. The release of relay 6 opens the circuit of and extinguishes the supervisory lamp 7; the release of relay 11 causes the release of relays 19 and 24. The conductor X is thereupon grounded through the outer right-hand alternate contact of relay 34 and the right-hand normal contact of relay 24. The deenergization of the above mentioned relays also grounds the signal-control conductor C10 over a connection which may be traced from ground, through the left-hand normal contact of relay 24, the outer left-hand alternate contact of relay 34, and the left-hand alternate contact of relay 13 to the conductor C10, relays 12, and 13 being maintained energized through the inner left hand alternate contact of relay 34. Thus the second of the two contacts associated with brush 202 of the selector switch SS, which contacts are allotted to the jack 10 of the trunk line L1, is grounded.

The motor magnet MM thereupon functions when the start relay 200 is energized by the grounding of the common starting conductor X, to advance all of the brushes of the selector switch SS until the brush 202 engages the contact connected with the grounded signal-control conductor C10, whereupon relay 201 operates and stops the motor magnet. The operation of the other sending apparatus at the office W will be the same as that previously described in connection with signaling impulses originating at office W, except that the combination of impulses sent over the common signaling conductor P to the office X, differs from that succeeding the insertion of the plug 1 into the jack 10, in that the polarity of the impulse sent over the selected signal-receiving conductor at the office X is positive rather than negative. The impulses received at the office X are distributed, as in the previous cases, by the receiving distributor R', and select the proper signal-receiving conductor E, as previously mentioned. This impulse of current flowing through the left-hand winding of relay 400, is of such a polarity that it differentializes such relay and causes it to release. The closure of the right-hand normal contact of relay 400 causes the illumination of lamp 405 over a circuit extending from battery through the normal contact of relay 400, the lower alternate contact of relay 406, and the lamp 405 to ground. The illumination of lamp 405 serves as a disconnect signal to the terminating operator at office X. The opening of the left-hand alternate contact of relay 400 opens the bridge across the trunk line L1, which includes the winding of supervisory relay 404. The battery supply relay 508 of the trunk circuit Q thereupon releases and the lamp 506 is illuminated before the toll switching operator over a circuit extending from battery through the lamp 506, the left-hand alternate contact of relay 503, the resistance 507, and the normal contact of relay 508 to ground. The illumination of the lamp 506 serves as a disconnect signal to the operator at the toll switching position of the office X. The terminating and toll switching trunk operators at the office X, in response to the signals displayed by the lamps 405 and 506, remove the plugs 407 and 500 respectively from the jacks 509 and 501, thereby restoring all apparatus to normal position, as shown in the drawings.

The subscriber at the station on the telephone line circuit T terminating at office X recalls the operator at office W.

Should the subscriber at the station on the line T, after the completion of a conversation with the office W over the trunk line L1 and the toll switching trunk Q,

established by means of the jack 10, desire to recall or signal the operator at office W, this result may be accomplished by repeatedly opening and closing the switchhook contacts at the station on the line circuit T. From the previous description it is evident that while the receiver at the station is removed from the switchhook so that the contacts thereof are closed, the supervisory relay 404 and other relays controlled by such supervisory relays are de-energized. Other relays associated with the incoming end of the trunk line L1 at the office X, such as the signal receiving relay 400 are energized while the signal-receiving relay 401 and the ringing relay 410 are de-energized. In response to the movements of the switchhook, relay 404 first operates and then releases. Relay 423 is made slow in releasing so that after being operated it is maintained in such condition during the short periods when the normal contact of the supervisory relay 404 is opened while the subscriber is repeatedly opening and closing the switchhook contacts. Relays 417 and 420 are also made slow in releasing to assist in the control of the recall signal before the operator at the office W when the subscriber at the station on the telephone line T is recalling the operator at the office W.

Upon the first opening of the switchhook contact supervisory relay 404 is energized, thereby energizing the relays 411, 412 and 413 as previously mentioned in connection with the completion of the connection between trunk line L1 and switching trunk Q. Relays 418 and 420 also operate as previously described. The automatic selector switch SS' at the office X advances until the brush 342 engages the contact to which the individual signal control conductor A'10 is connected. The sending apparatus at office X functions, as previously described, to transmit the same combination of impulses over the common signaling path P to the office W, and such impulses are received at the office W in the same manner as described in connection with the completion of a connection and the transmission of the ringing signal from the office W to the office X. Signal-receiving relay 27 is energized and locked by the last impulse of the series, so that the marginal relay 6 of the cord circuit operates due to the shunt path, including the resistance 26, established around the winding of relay 11. Relay 28 is released by the energization of relay 27. The supervisory lamp 7 is illuminated due to the operation of the supervisory relay 6.

The closure of the switchhook contact shortly after the opening thereof causes the release of the supervisory relay 404 as in the case of the answer of the called party. The opening of the alternate contact of relay 404

breaks the locking circuit for relay 412 which thereupon releases said relay being only slightly slow to release so that its armatures will be fully retracted before contact of relay 404 is again closed. The release of relay 404 also established a circuit for slow to release relay 423 extending from battery through the winding of relay 423, the alternate contact of relay 411 which remains energized during the opening and closing of the contacts of relay 404, the normal contact of the latter relay and the normal contact of relay 414 to ground. Relay 423 is also sufficiently slow to maintain its alternate contact closed during the operation of relay 404. Upon the second operation of the supervisory relay, relays 412 and 413 are again energized as previously described to effect the transmission of the same combination of impulses to the office W as were transmitted upon the first operation of relay 404. Inasmuch as the relay 420 is operated at the time of the second operation of relay 404 a circuit is established upon the second energization of relay 413, which circuit is traceable from battery through the right hand alternate contact of relay 400, the right hand normal contact of relay 419, the winding and right hand normal contact of relay 417, the left hand alternate contact of relay 420 and the inner left hand alternate contact of relay 413 to ground. Relay 417 energizes and locks through its right hand alternate contact to ground at the inner right hand normal contact of relay 416. When the supervisory relay 404 next releases, relay 412 does not release as in the previous instance, but is maintained energized through the inner left hand alternate contact of relay 417. If the supervisory relay 404 now continues to operate and release, no other relay will be operated and therefore no further signals will be transmitted as long as relays 411 and 423 are energized.

The impulses of the second combination are received at the office W and distributed in the same manner as previously described. The last impulse of such series, being of the same character as that flowing through the locking winding of relay 27, produces the effect thereupon, but in flowing through the left-hand winding of signal-receiving relay 29, causes the latter relay to operate and lock. The closure of the left-hand alternate contact of relay 29 includes interrupter 36 in series with the branch circuit including the resistance 26, which was previously established around the winding of relay 11. This circuit is now traceable from ground, the interrupter 36, the left-hand alternate contacts of relays 29 and 27, the resistance 26, the inner right hand contact of relay 13, to the sleeve contact of jack 10. The interrupted ground furnished to this shunt path causes the intermittent operation and re-

- lease of marginal supervisory relay 6, which causes the flashing of the supervisory lamp 7 at a predetermined rate, depending upon the speed at which the interrupter 36 is continuously rotating. This intermittent lighting of the lamp serves to indicate that the subscriber at the station on the line circuit T desires to recall the operator at the office W. This flashing recall is continued after 5 the second opening of the switchhook contact of the station on the line circuit T, although, as previously mentioned, no more signals are transmitted over the signaling path during the continued rapid opening 10 and closing of the switchhook contacts. However, it is necessary to continue to rapidly open and close the switchhook contacts to maintain the signal lamp in connection with the interrupter 36.
- 10 If, after repeatedly opening and closing the switchhook contacts the subscriber should leave the contacts closed, then the supervisory relay 404 is deenergized for an extended period. Relays 411, 423 and 416 15 are controlled by such supervisory relay to function in the manner described in connection with the transmission of the answering signal from the office X to the office W, which causes the common signaling apparatus at the two offices to transmit and receive 20 the same combination of impulses as in the case of the transmission of the answering signal. The last impulse transmitted in this manner is of the proper polarity to differentiate both of the signal-receiving relays 27 and 29, whereby the interrupter 36 is removed from its circuit relation with the marginal relay 6 so that the supervisory lamp 7 is permanently extinguished to indicate that the subscriber's telephone set remains connected to the telephone line. 25
- If, after repeatedly opening and closing the switchhook contact, the subscriber should leave such contact open, the supervisory relay 404 would then be energized for an extended period. This extended energization of the supervisory relay causes the release of relay 423 and operation of relay 416 to function in the same manner as in the case of the transmission of the disconnect signal. These relays cause the common transmitting and receiving apparatus at the offices X and W respectively to transmit a code of impulses which will extinguish the supervisory lamp 30 7. Then upon the release of relay 416, relays 412 and 413 operate to transmit a signal similar to the disconnect signal which energizes relay 27 and causes the illumination of the supervisory lamp 7 of the cord circuit. 35
- Through calls the operator at office W extends a call to the telephone line circuit T terminating at office Y.
- Assuming that the operator at office W 40 desires to extend a connection to a station on the line circuit T terminating at office Y, which station must be reached through the office X and a toll switching trunk at office Y, similar to the trunk Q, the plug 1 of the cord circuit O at the office W is inserted 45 into the jack 20 of the toll line circuit L1 which line circuit has been found to be idle by testing or otherwise. In this case the figures should be arranged as shown in Fig. 14. Relay 21 operates over a circuit extending from battery through the winding of marginal supervisory relay 6, the sleeve contacts of plug 1 and jack 20, the winding and right-hand normal contact of relay 21, to the contact of relay 19. Relay 21 locks 50 over a circuit including the winding and inner right-hand alternate contact of relay 21 and the winding of relay 19 to ground, the latter relay thereupon operating. The operation of relay 19 removes the ground 55 from the testing conductors leading to the preceding offices to render the trunk circuit L1 non-selectable from such offices, as is clearly shown in Fig. 7 and described in connection therewith. Relay 16 operates over a circuit extending from battery through the winding of relay 16 and the outer right-hand alternate contact of relay 21 to ground. The operation of relay 16 connects the talking conductors leading from 60 jack 20 to the talking conductors of the trunk line L1, extending to the distant office X and disconnects the talking conductors leading from the jack 10. Relays 22 and 23 also operate under control of the relay 21, and the operation of relay 23 causes the operation of relay 24 over a circuit which may be traced from battery through the outer right-hand alternate contact of 65 relay 23, the winding of relay 24, and the normal contact of relay 34 to ground. Relay 24 thereupon locks through its winding and inner left-hand alternate contact to ground at relay 21. Relay 34 thereupon operates over an obvious circuit and locks 70 through its left-hand winding and the inner left-hand alternate contact. The individual signal control conductor A20 is grounded through the outer left-hand alternate contact of relay 24, and the left-hand contacts of relays 25 and 35. The common starting conductor X is also grounded through the outer right-hand alternate contacts of relays 34 and 24, the right-hand contact of relay 25 and the inner left-hand normal contact of relay 35. The grounding of these 75 two conductors causes the common impulse transmitting apparatus at office W to function in a manner similar to that previously described when the individual signal-control conductor A10 was grounded simultaneously with the starting conductor X. However, a different combination of impulses is sent over the common signaling path due to the connection of different polarities of current 80

to the sending segments of the sending distributor S by the various brushes of the selector switch SS, so that when these impulses are received by the common receiving apparatus at the office X, different relays controlled by distributor R' will be operated and locked to select the signal-receiving conductor E2 and to transmit thereover an impulse of negative polarity. This impulse will be received by the signal-receiving relay 424.

After the transmission of the impulses from the office W, the brush arm 204 of the selector switch SS thereat completes a circuit including the relay 35 which thereupon operates and locks to disconnect the ground connection from the common starting conductor X and the individual signal-control conductor A20. The energizing circuit for relay 35 may be traced from battery through the contact of relay 203, the contact of relay 205, the brush arm 204 and the contact in engagement therewith, the conductor B20 (Fig. 1) the inner right-hand alternate contact of relay 22, the winding of relay 35, the right-hand contact of relay 25, the outer right-hand alternate contact of relay 24, and the outer right-hand alternate contact of relay 34 to ground. Relay 35 locks through its right-hand contact.

Relay 424, in operating, locks over a circuit extending from battery through the winding of relay 419 and the right-hand winding of relay 424 to ground at the middle alternate contact of the latter relay. Relay 419 thereupon operates and by the closure of its left-hand alternate contact connects ground to the conductor R leading to the motor magnet MM6 to start the operation of such magnet. The closure of the right-hand alternate contact of relay 424 connects ground from the left-hand normal contact of relay 425 through the right-hand alternate contact of relay 424 to the conductor P1 leading to the line switch LS1. The motor magnet MM6 thereupon advances the brushes 600 and 603 inclusive until the brush arm 601 engages the contact to which the grounded conductor P1 is connected, thereby extending the ground connection through the winding of relay 607 to grounded battery. Relay 426 thereupon operates over a circuit extending from battery through the left-hand winding of relay 426, the outer right-hand normal contact of relay 425 the conductor 427, leading to the brush arm 601 and the grounded conductor P1. Relay 426, in operating, completes an obvious locking circuit for itself. The operation of relay 426 opens the normal contact thereof to open the R lead which controls the motor magnet MM6, so that such motor magnet ceases its operation and the various brushes controlled thereby remain in their attained position. The closure of the left-

hand alternate contact of relay 426 closes the filament circuit of the repeater or amplifier R 428, and the ground connected through the right-hand alternate contact of relay 426 causes the operation of switching relay 409 to transfer the talking conductors of trunk line L1 leading from the office X from their normal connection with the plug 407 to the amplifier R 428, so that the talking circuit is now connected through the jack 20 at the office W to the brush arms 605 and 606 of the line switch LS1. The closure of the contact of relay 607 also completes a circuit from battery through the windings and contacts of motor magnets MM7 and MM8 in parallel, the contact of relay 607 to ground on the conductor P1. Thus the motor magnets MM7 and MM8 start operating to advance the various associated brushes step by step over their respective banks of contacts until the brush 608 finds an idle test lead 609 which extends to a trunk circuit having such lead grounded. Assuming that this is the trunk circuit L1 extending from the office X to the office Y, relay 425 operates upon the arm 608 engaging the contact connected with the test lead 609 leading to such trunk, the circuit for such relay being traceable from battery through the left-hand winding of relay 425, conductor 429, the brush arm 608, the contact engaged thereby, the conductor or test lead 609, the left-hand normal contact of relay 711, and the left-hand normal contact of relay 719 to ground. The opening of the left-hand normal contact of relay 425 opens the maintaining circuit for relay 607, which releases to open the operating circuits for motor magnets MM7 and MM8, so that the further operation of such motor magnets is prevented and the brush arms associated therewith occupy their attained position. Relay 425, in operating, locks through its right-hand winding and alternate contact, and the middle alternate contact of relay 424 to ground. The closure of the left-hand alternate contact of relay 425 connects a source of current with the conductor 430, in which the winding of marginal relay 414 is inserted. At this time the talking conductors are connected through the brush arms 605 and 606 of the line switch LS1 and the brush arms 613 and 614 of the line switch LS2 and the tip and ring respectively of the trunk line L1 at the outgoing end of office X. The repeater set including the repeater 428, the balancing network 440 permanently associated therewith, and the selected balancing network 737, is now built up through the brushes 603 and 604 of the switch LS1 and brushes 611 and 612 of the switch LS2 so that the trunk line is properly balanced. The closure of the filament circuit of the repeater by means of the operation of relay 426, as previously mentioned,

- renders the repeater set effective and in readiness to transmit talking current. The sleeve conductor 738 is also connected through the brush arm 610 of the line switch 5 LS2 and the brush arm 602 of the line switch LS1 to conductor 430 so that a circuit is completed from battery through the left-hand alternate contact of relay 425, the winding of marginal relay 414, the conductor 10 430, the brush arms 602 and 610, the sleeve conductor 738, the winding of relay 711, the right-hand normal contact thereof, and the right-hand normal contact of relay 719 to ground. Relay 711 immediately 15 operates, the opening of the left-hand normal contact thereof removing the ground from the test lead 609. The closure of the inner right-hand alternate contact of relay 711 completes a locking circuit for such relay, 20 which extends through the winding of relay 719. The latter relay operates over such circuit, removing the ground from all of the testing leads 609, 621, and 622, rendering the trunk line L1, extending from the office 25 X, inaccessible to calls proceeding to such office. The opening of the right-hand contact of relay 719 prevents the sleeve relays 721 and 731 from being energized if the sleeve conductors 739 and 740 are selected. 30 The closure of the outer right-hand alternate contact of relay 711 causes the operation of relay 712 and 713 over obvious circuits and the operation of said relays results in the grounding of the starting conductor X2 and the signal control conductor A10. The operation of grounding these conductors being the same as that in Figure 1, reference is made to the description of the latter figure, the reference numerals 35 in Figure 7 being the same for corresponding elements except that the hundreds digit "7" is added.
- The grounding of the two conductors causes the associations of the common sending apparatus at office X, such as shown in Figure 2, with the trunk line L1 leading to the office Y, in a manner similar to that described in connection with the association of the common sending apparatus with the 40 trunk line L1 at office W. Since the sending apparatus is exactly the same as that at office X, a detailed description is not thought necessary. However, such sending apparatus is caused to transmit a combination of impulses over the common signaling path P to the common receiver apparatus at office Y, which receiving apparatus is exactly the same as that employed at office X and described in connection with the signals transmitted 45 to the latter office from office W. Immediately upon the transmission of the impulses, the conductor B10 at office X is connected to battery so that relay 735 is operated over a circuit extending from the 50 battery connected to conductor B10 in connection with the common sending apparatus, the inner right hand alternate contact of relay 712, the winding of relay 735, the right hand contact of relay 725, and the outer right hand alternate contacts of relays 724 and 734 to ground. Relay 735 is locked through its right hand alternate contact and winding. The opening of the inner left hand normal contact of relay 735 removes the ground from the common 55 start conductor X2 while the opening of the outer left hand normal contact of said relay interrupts the continuity of the ground connection to the individual signal control conductor A10. The common sending apparatus is thereupon restored to its normal condition in the same manner as previously described and rendered available for use in connection with other trunks.
- Upon the receipt of the combination of 60 impulses at office Y, the receiver distributor R' located thereat is caused to distribute the impulses through the various locking relays controlled thereby for the purpose of selecting the signal receiving conductor E at 65 office Y and for transmitting thereover an impulse of negative polarity. Immediately upon the transmission of this impulse the common receiving apparatus at office Y is restored to its normal condition and rendered 70 available for use with other trunks.
- The last mentioned impulse flowing through the left hand winding of relay 719 causes the operation of this relay which results in the illumination of the guard lamp 80 705 in the same manner as described in connection with lamp 405. For a complete description of this operation, reference is made to the description of Figure 4, the tens and units digits of the reference numerals in 75 Figures 4 and 8 being alike.
- The connection of toll switching trunk Q at office Y with the telephone line circuit T and of the trunk L1 terminating at office Y with the toll switching trunk Q.*
- The operations of connecting the toll switching trunk circuit Q at office Y with the telephone line circuit T and the connection of the trunk line circuit L1 terminating 80 at said office with the toll switching trunk Q are the same as previously described in connection with offices W and X. The latter operation causes the energization of the relay 813 in the same manner as described in connection with relay 413. The conductors X' and A'10 (Figure 8) are thereby grounded. The grounding of the two conductors just mentioned causes the common sending apparatus at office Y to become associated with 85 the trunk line L1 and to transmit over the path the P leading to office X a combination of impulses similar in character to that which was transmitted from office X to office 90 W when the connection with the telephone 95 100 105 110 115 120 125 130

line circuit T terminating at said office had been established. Immediately upon the transmission of such impulses as in the previous instance, the conductor B at office Y is connected to battery to cause the operation of relay 815 with the same result as described in connection with relay 415. These impulses are received at office X and are caused to select the receiving conductor E' thereat and 10 to transmit thereover an impulse of negative polarity as was described in connection with the establishment of the connection between offices W and X. This impulse received at office X causes the operation of relay 727. 15 This relay locks and places the resistance 726 in shunt around the winding of relay 711 in the same manner described in connection with Figure 1. Thus sufficient current is permitted to flow over the circuit path including the sleeve conductor 738, brush 610 of the line switch LS2, the brush 602 of the line switch LS1, the conductor 430, the winding of marginal relay 414, and the inner left hand alternate contact of relay 425 to battery to cause marginal relay 414 to operate. Relay 414 now, in effect, replaces the supervisory relay 404. The operation of relay 414 causes 20 the energization of relay 411 over a circuit traceable from battery through the winding 411 and the alternate contact of relay 414 to ground. Relay 412 also operates over circuit extending from battery through the winding and right hand normal contact of 25 said relay, the right hand contact of relay 415, the outer right hand normal contact of relay 416 and the alternate contact of relay 414 to ground. Inasmuch as relay 412 is slightly slow to operate a circuit will be 30 established for relay 413 before relay 412 has fully operated, said circuit extending from battery through the common starting relay 341, the common starting conductor X', the inner left hand normal contact of 35 relay 415, the winding and inner right hand normal contact of relay 413, the left hand normal contact of relay 412 and from thence over the energizing circuit of the latter relay. The operation of relay 413 again results in 40 the transmission of a combination of impulses to office W in the same manner as previously described to notify the operator at said office that the connection has been established. The relay 27 is operated and the lamp 7 illuminated in this operation. 45

Upon the transmission of the above impulses the sending apparatus is removed from its association with the trunk line L1 at office X and again made available for use with other calls. 50

The operator at office W actuates the ringing key.

The operator at office W, observing the 55 lighted condition of the supervisory lamp 7,

actuates the ringing key 2 which completes a circuit from the source of ringing current through the lower alternate contact of key 2, the ring contacts of plug 1 and jack 20, the lower alternate contact of relay 16, the condenser 18, the winding of relay 17, the upper alternate contact of relay 16, the tip contacts of jack 20 and plug 1, and the upper alternate contact of ringing key 2 to ground. Ringing response relay 17 thereupon 70 operates to close an energizing circuit for slow-release relay 25. Relays 17 and 25 are maintained in an operated condition while the ringing key remains operated, but release when the current flow is discontinued. Relay 25, in operating, opens the locking circuit of and thereby permits the release of relay 35. As in the previous instance, no signal is transmitted during the ringing period to the distant office. 75

The operator at office W releases the ringing key.

Upon the restoration of the ringing key 2 to its normal position, ringing response relay 17 and slow-release relay 25 release. A ground connection is thus completed from the outer right-hand alternate contact of relay 34, the outer right-hand alternate contact of relay 24, and the right-hand contact of relay 25, the right-hand normal contact of relay 35 to the common start conductor X. A ground connection is also established from the outer left-hand alternate contact of relay 24, the left-hand normal contacts of relays 25 and 35 in series, the outer right-hand alternate contact of relay 22 to the individual signal-control conductor A20. The grounding of these two conductors causes the association of the common signal-transmitting apparatus with the trunk line L1 and the sending of a combination of impulses by such apparatus, which corresponds with that originally transmitted in response to the insertion of the plug 1 into the jack 20. These impulses flow over the common signaling path P to the office X, as previously described and are received thereat by the common receiving apparatus including the receiving distributor R', and cause the locking of the same relays mentioned in the previous case. Thereby the apparatus selects the signal-receiving conductor E2 and sends thereover an impulse of current of negative polarity. Relays 424 and 419 having been 105 previously operated and locked, the conductor 431 thereby receives a momentary impulse of current over a circuit which may be traced from the conductors E2, through the left-hand alternate contact of relay 424, the conductor 431, the brush arm 600 of the line switch LS1 and the brush arm 608' of the line switch LS2 and the left-hand winding of relay 623 to ground. Relay 623, in operating, locks over a circuit extending from 110

battery through the right-hand winding and contact of relay 623 and the contact of relay 714 to ground. After the cessation of the impulse, the common receiving apparatus at office X is restored to its normal condition as in the previous instances.

Relay 715 is operated by the energization of relay 623 over a circuit extending from battery through the winding of relay 715, the contact of relay 623 and the contact of relay 714 to ground. The closure of the left-hand contact of relay 715 completes an energizing circuit for slow-release relay 725, while the closure of the right-hand contact of relay 715 causes the energization of relay 714 over an obvious circuit, thereby causing the release of relay 623. Relay 725, when energized, opens the circuit of and causes the release of relay 735. Upon the energization of relay 714, relay 715 deenergizes to cause the deenergization of relay 725, thereby restoring these relays to normal. The common start conductor X2 at office X is then grounded over a circuit extending from ground through the outer right-hand alternate contacts of relays 724 and 734 in series, the right-hand contact of relay 725, and the right-hand normal contact of relay 735 to the common start conductor X2. At the same time the individual signal-control conductor A10 is grounded in the same manner as previously described.

The grounding of the starting conductor X2 and the signal-control conductor A10 causes the association of the common impulse-sending apparatus with the trunk line L1 leading from the office X to the office Y, and further causes the sending apparatus to transmit a combination of impulses to the office Y over the common signaling path P interconnecting such offices, as was transmitted between the offices W and X. These impulses, upon being received at office Y, cause the apparatus thereat to so function as to select the individual signal-receiving conductor E thereat and to send an impulse of negative polarity thereover. This current, being of the same polarity as that flowing through the locking winding of relay 800, produces no effect upon such relay, altho such current flows through the right-hand winding of relay 801 over a path including the contact of relay 802. Relay 801 thereupon locks temporarily over a circuit extending from battery through the left-hand alternate contact of relay 801 and the contact of relay 803 to ground, the latter relay having been energized by the operation of relay 800. The opening of the normal contact of relay 801 causes the release of slow-release relay 803 which, upon its complete release, causes relay 801 to de-energize. However, during the interval that relay 801 remains locked, a circuit is com-

pleted from battery through the right-hand alternate contact of relay 800, the right-hand alternate contact of relay 801 and the winding of slow-release relay 821 to ground. Relay 821, in operating, completes an obvious operating circuit for slow-release relay 822. Therefore, during the period that relay 821 remains in operated condition, a circuit is completed from battery through the winding of relay 810, and the right-hand alternate contact of relay 821 to ground. The operation of relay 810 completes a circuit to apply ringing current to the line circuit T in the same manner as previously described with the result that the bell at the sub-station is rung. The ringing circuit is completed during the functioning of the slow-release relays controlling the operation of relay 810. The ringing current is removed from the trunk line L1 terminating at office Y and from the toll-switching trunk Q and the associated telephone lines after the predetermined interval controlled by said slow relays has elapsed. Therefore, in response to the restoration of the ringing key to normal after each impulse of ringing current applied to the conductors of the trunk line L1 through the jack 20 at the office W, the ringing current is applied for a predetermined period to the line T to operate the bell thereat.

The called subscriber at the station on the telephone line circuit T removes the receiver from the switchhook.

The subscriber at the station on the line circuit T, terminating at the office Y, in response to the signal given by the bell at such station, removes the receiver from the switchhook to control the operation of the relays in the toll switching circuit as previously described. As in the previous case, a supervisory relay 804 is deenergized due to the opening of the circuit thereof, and in releasing initiates the operation of relays in Figure 8 corresponding to those in Figure 4 and numbered alike with the exception of the hundreds digits. This operation as described in connection with Figure 4, results in the operation of relay 816 with a consequent grounding of the start conductor X' and signal control C'10. The grounding of these two leads causes the association of the common sending apparatus at the office Y with the trunk line circuit L1 and the functioning thereof to transmit a code of impulses over the common signaling path P to the office X. The combination of impulses sent in this case is the same as that in the case of the call which was extended to the telephone line circuit T terminating at office X when the subscriber's receiver at the station on the telephone line is removed from the switchhook,

Therefore, the impulses as received by the common receiving apparatus at the office X are employed to select the signal receiving conductor E' and to cause a current flow 5 of positive polarity over such conductor. This current flowing through the left-hand windings of relay 727 is of the proper polarity to differentialize said relay and cause its release. The release of relay 727 inter- 10 rupts the shunt path around the winding of relay 711 which includes resistance 726. Therefore, the amount of current flowing through the sleeve conductor 738 over the brushes 610 of the line switch LS2 and 15 602 of line switch LS1, the conductor 430, the winding of marginal relay 414 and the left-hand alternate contact of relay 425 to battery, is decreased sufficiently to cause the release of the marginal relay 414. Upon 20 the transmission of the combination of impulses from the office Y, battery is connected to the conductor B thereat, causing the operation of relay 815 to initiate the restoration of the common sending apparatus at the office Y and the common receiving apparatus at the office X.

The release of marginal relay 414 connects ground to the conductor associated with the normal contact of relay 404 which 30 is now employed with this through connection in the same manner as in the case where such relay was employed in connection with extending a call to a telephone line circuit terminating at the office X. Relay 416 is 35 thereupon operated over the common starting lead X'. The operation of relay 416 also causes the grounding of the individual signal-control conductor C'10. The grounding of these two conductors, as in 40 the previous instances, causes the association of the common sending apparatus at the office X with the trunk line L1, extending from the office X to the office W, which sending apparatus thereupon functions in 45 the same manner as in the case of the answer of the subscriber's station on the telephone line T, terminating at office X. The same combination of impulses being sent over the common signaling path P to the 50 office W, causes the receiving apparatus thereat to function in the same manner as before to select the signal-receiving conductor E' and to transmit thereover an impulse of positive polarity which in flowing 55 through the left-hand winding of relay 27 differentializes such relay and causes it to release. This results in the extinguishment of lamp 7. After transmitting such impulses to the relay 27, all of the receiving apparatus common to the office W is 60 restored to normal. The extinguishing of the lamp 7 serves as an indication to the operator at office W that the desired party on the telephone line T, terminating at office Y, has

responded. The transmission circuit is now 65 in condition so that the interconnected parties may converse thereover as outlined previously.

The subscriber restores the receiver to the switchhook.

At the conclusion of the conversation, the subscriber at the station on the line circuit T, terminating at office Y, restores the receiver to the switchhook to release supervisory relay 513 of the toll switching trunk Q. Referring now to the foregoing description of Figure 4 wherein the action of the relays is related upon the restoration of the receiver to the switchhook and applying such description to Figure 8, it will be apparent that supervisory relay 804 of the trunk line L1, terminating at office Y will operate. This results in the operation of relay 813. The operation of the latter relay connects ground to the signal control conductor A'10, and since the common start conductor X' is grounded, the common sending apparatus at the office Y is again associated with the trunk line circuit L1 and 90 functions to transmit over the common signaling path P to the office X a combination of impulses of the same character as that transmitted in response to the insertion of the plug 807 into the jack 509 of the trunk circuit Q. These impulses are received at the office X in the same manner as previously described for the selection of the signal-receiving conductor E' and the transmission thereover of the current impulse of 95 negative polarity. As in the previous case, upon the transmission of the impulses from the office Y, the conductor B'10 is connected to battery to cause the operation of relay 815 which, in operating, disconnects the ground from the common start conductor X' and causes the deenergization of relay 813 which disconnects the ground from the individual signal-control conductor A'10, thereby 100 restoring all of the common sending apparatus at the office Y to its normal condition.

The transmission of the final impulse which is of negative polarity over the receiving conductor E', causes the operation of relay 727 which immediately locks as previously described, and includes the resistance 726 in a shunt path around the winding of relay 711, as previously described, thereby increasing the current flowing over the conductor 738 sufficiently to cause the 105 operation of marginal relay 414 at office X. The circuit for this latter-mentioned relay is the same as that previously traced therefor. The operation of relay 414 performs the same function at office X as the operation of supervisory relay 404 performs in response to the restoration to the switchhook 110 of the receiver at the station on the tele- 115

phone line circuit T terminating at office X, and as was previously described in connection with the insertion of the plug 807 into the jack 509 of the trunk circuit Q. Therefore, it is thought that it will not be necessary to repeat the detailed description of the operation of the apparatus further than to state that the common starting conductor X' is grounded and the individual signal control conductor A'10 is also grounded, causing the common signaling apparatus at the office X to become associated with the trunk line L1 and to transmit over the common signaling path P to the office W, the same combination of impulses as mentioned in connection with the previous cases. Upon the transmission of such impulses, the battery is connected to the conductor B which restores the individual signal sending apparatus at the office X to its previous condition. The receipt of these impulses at the office W again causes the selection of the signal receiving conductor E' as in the previous instances and the transmission thereover of an impulse of negative polarity which, in flowing through the left-hand winding of relay 27 places resistance 26 in parallel relation with the winding of relay 21. The marginal relay 6 of the cord circuit O then receives sufficient current to cause its operation and the consequent lighting of the supervisory lamp 7 over an obvious circuit as previously described. The illumination of the lamp 7 serves as a disconnect signal to the operator at the office W.

The operator at office W disconnects the toll cord circuit O from the trunk line L1.

The operator at office W, upon observing the lighted condition of the supervisory lamp 7 withdraws the plug 1 from the jack 20, causing the release of relays 6, 21, 19 and 16. The release of relay 6 extinguishes the supervisory lamp while the release of relay 16 disconnects the talking conductors of jack 20 from the outgoing conductors of the trunk line L1 and connects the latter-mentioned conductors to the talking conductors of the jack 10 as shown on the drawing. The release of relay 19, prepares circuits for all of the relays 11, 21 and 31, so that they may respond upon the insertion of a plug into the corresponding jack. The release of relay 21 also causes the release of relay 24, which causes the release of relay 35. The common start conductor X is thereupon grounded over a circuit traceable from ground through the outer right-hand alternate contact of relay 34, the right-hand normal contact of relay 24, to the start conductor X, while the individual signal-control conductor C20 is also grounded over a path extending from ground through the left-hand normal contact of relay 24, the outer left-hand alternate contact of relay 34, and the left-hand alter-

nate contact of relay 23 to the conductor C20. It will be noted that relays 22 and 23 are maintained in their operated condition due to the ground being supplied to their locking windings through the inner left-hand alternate contact of relay 34. The grounding of these conductors causes the association of the common signal impulse-sending apparatus at office W with the trunk line L1, which, in response thereto, functions to transmit a combination of impulses over the common signaling path P to the office X, which differs from that previously transmitted thereover only in that the polarity of the last or signaling impulse differs from that previously sent. During the transmission of the impulses from the office W and while relay 205 is operated, an impulse of current is sent over the conductor D20 through the contacts of relays 203 and 205 and flows through the inner left-hand alternate contact of relay 22 and the inner right-hand alternate contact and the right-hand winding of relay 34 to ground. This current, being of the proper polarity differentiates and causes the release of relay 34. Relay 34, in deenergizing, removes the ground connections from the common start conductor X and the signal-control conductor C20, and in opening its inner left-hand alternate contact, removes the ground from the holding circuit traced for relays 23 and 22, which thereupon release, restoring the apparatus at office W to its normal condition.

These impulses, upon their receipt at office X, select the signal-receiving conductor E2 (Fig. 4) as in the previous instances, and due to the difference in the polarity of the last impulse transmitted over such conductor, relay 424 is differentialized and releases, and relay 419 also releases. The opening of the inner right-hand alternate contact of relay 424 opens the locking circuit of relay 425, and the opening of the left-hand alternate contact of such relay removes the battery connection from the circuit including the winding of marginal relay 414 which thereupon releases. Relay 426 is also deenergized to cause the deenergization of relay 409, thereby restoring the continuity of the talking conductors of the trunk line L1 terminating at office X to the respective contacts of plug 407. No effect is produced upon the line switches LS 1, 2 and 3 by the removal of battery from the circuit including the winding of relay 414, and the brush arms of such switches remain in their attained positions until they are called into service in connection with the extension of another call. However, the removal of the battery from this circuit which was previously traced, removes battery from the conductor 738 associated with the jack 710, at the office X, whereupon relay 711 releases; but due to

the locking circuits of relay 712 and 713 controlled by relay 734, the former relays do not release at this time. Relay 719 releases due to the release of 711 to restore to normal 5 the testing conductors of the trunk line L1 extending from the office X to the office Y. The closure of the right-hand normal contact of relay 719 prepares circuits for the operation of relays 711, 721 and 731 respectively, 10 so that they may respond to the connection of the plug with their associated jacks 710, 720 and 730. The opening of the lower right-hand alternate contact of relay 711 causes the release of relay 724. Relay 735 also releases due to the opening of the outer right-hand alternate contact of relay 724, whereupon the common starting conductor X2 is grounded over a circuit the same as previously described in connection with Figure 1. The individual signal control conductor C10 is also grounded in the same manner that conductor C20 was grounded. By the grounding of these conductors, the common sending apparatus at the office X is associated with the trunk line L1 extending from office X to office Y and functions in a manner similar to that described in connection with signals which have been transmitted heretofore from the office X to the office Y. However, the polarity of the last impulse of the combination is different from that of the similar impulse sent in the previous cases. The sending apparatus, upon transmitting all of the impulses, connects 35 battery to the control conductor D10, which flows through the inner right-hand contact and right-hand winding of relay 734 to ground. Relay 734 thereupon releases disconnecting the ground connections from the common starting conductor X2 and individual signal-control conductor C10. The opening of the inner left-hand alternate contact of relay 734 removes ground from the holding circuits of relay 712 and 713 and 40 causes the release of such relays. Thus all of the individual sending apparatus at the office X is restored to normal, and as a consequence, all of the common sending apparatus is also restored to normal.

These impulses, upon their receipt at the office Y, again select the receiving conductor E, and cause an impulse of positive polarity to flow over such conductor through the left-hand winding of relay 800. The polarity of this impulse is such as will differentialize and release relay 800. The closure of the right-hand normal contact of relay 800 completes a circuit which extends from battery through said contact, the alternate contact of relay 806, and the lamp 805 to ground. A branch of this circuit includes the winding of slow-release relay 802 which removes the right-hand winding of relay 801 from its normal association with the receiving conductor E. The opening of the

left-hand alternate contact of relay 800 opens the bridge across the trunk line circuit L1, which bridge includes the winding of relay 804, so that such relay releases. The opening of this bridge causes the release of battery supply relay 508 of the trunk circuit Q, whereby lamp 506 is illuminated before the toll switching operator over an obvious circuit to serve as a disconnect signal to such operator. The illumination of lamp 805 at the terminating operator's position serves as a disconnect signal to such operator, and both operators in response to such disconnect signals may remove the plugs 807 and 500 from the jacks 509 and 501 respectively, thereby restoring all apparatus to normal position, as shown in the drawings.

The subscriber at the station on the telephone line circuit T terminating at office Y recalls the operator at office W.

Should the subscriber at the station on the telephone line circuit T, after the completion of the conversation with the office W over the trunk lines L1 interconnecting the office X with the office W and Y and the toll switching trunk circuit Q, which was established by means of the jack 20 at the office W, desire to recall or signal the operator at the latter office before the connection has been taken down, this result may be accomplished by repeatedly opening and closing the switchhook contacts at such station. From the previous description, it is evident that while the receiver is removed from the switchhook so that the contacts thereof are closed the supervisory relay 804 and other relays controlled by such relay, are deenergized. Thus supervisory relay 804 will follow in its operation the actuation of the switchhook. In response to the first opening of the switchhook contacts, relay 804 operates, in the same manner that relay 404 energized, to effect the operation of relays 811, 812 and 813 as described in connection with relays 411, 412 and 413. The energization of relay 813 causes the operation of relay 727 by the transmission of a code of impulses over the common signaling path between offices Y and X. As in the previously described instance, conductor 738 is grounded through the resistance 726 to cause the operation of relay 414. The relay mechanism at office X (Fig. 4) then operates to effect the transmission of a combination of impulses to office W. This results in the operation of relay 27 and consequent lighting of the lamp 7. The next actuation of the switchhook in which the contacts thereof are closed causes supervisory relay 804 to release. The operation is then the same as that described in connection with Figure 4, resulting in the energization of relay 729 at office X. The impulse which operates relay

729 is then repeated by the actuation of the relay mechanism of Figure 4. As a result thereof, relay 29 at office W is operated to include the interrupter 36 in series with the 5 winding of relay 6. The lamp 7 is therefore flashed to recall the operator at office W. As previously described, the flashing recall continues after the second opening of the switchhook contact but no more signals are 10 transmitted.

If, after repeatedly opening and closing the switchhook contacts the subscriber should leave the contacts closed, the relays 727, 729, 27 and 29 are differentialized to 15 permanently extinguish the lamp 7. The release of the former two relays is accomplished in the same manner as described in connection with the latter two. The extinguishment of the lamp indicates to the operator at office W that the subscriber is still connected to the line.

If, after repeatedly opening and closing the switchhook contact the subscriber should replace the receiver upon the hook, the apparatus functions as in the case of the disconnect signal. It is believed that by reference to the previous description the operation of the relays at the various offices will be understood. The final result is that the 30 lamp 7 is lighted and the operator then proceeds to disestablish the connection.

The operator at office W extends a call to a telephone line circuit T terminating at the office Z.

Let it be assumed that the operator at office W desires to extend a connection to a station on the line circuit T, terminating at office Z, which station must be reached through the intermediate offices X and Y and a toll switching trunk at office Z. In this instance the circuits are arranged as shown in Figure 15. The operator at office W inserts the plug 1 of the cord circuit 0 40 into the jack 30 of the trunk line L1 extending from the office W to the office X. Relay 31 operates over a circuit extending from battery through the winding of marginal relay 6, the sleeve contacts of plug 1 and jack 30, the winding of relay 31 and the contact of relay 19 to ground. Relay 6 is marginal and does not operate due to the current flowing through this circuit. However, relay 31 operates and becomes locked 45 in the same manner as described in connection with relays 11 and 21. Relay 19 operates in response to current flowing over this locking circuit. The opening of the right-hand contact of relay 19 removes ground from the energizing circuits of relays 11 and 21 so that they may not be operated in case a plug is inserted into their associated jacks 10 and 20 while a plug is in jack 30. The 50 closure of the upper right-hand alternate contact of relay 31 operates relay 16 over

an obvious circuit, to disconnect the outgoing conductors of trunk line L1 from their normal association with the tip and ring contacts of jack 10 and to connect them to the tip and ring contacts of jack 30. Relays 32 and 33 operate upon the energization of relay 31 over obvious circuits including their left-hand windings. The operation of relay 33 causes the operation of relay 24 over a circuit extending from battery 55 through the outer right-hand alternate contact of relay 33, the winding of relay 24, and the normal contact of relay 34 to ground. Relay 24, in operating, causes the operation of relay 34 over an obvious circuit which 60 also locks over an obvious circuit. Relay 24 also, in operating, causes a locking circuit to be completed therefor which extends through the winding and inner left-hand alternate contact of relay 24, and the lower 65 right-hand alternate contact of relay 31 to ground. Relays 32 and 33 are also locked due to the operation of relay 34, the circuit therefor being traced in parallel from battery through the right-hand windings of 70 relays 32 and 33, the outer left-hand alternate contact of relay 32, and the inner left-hand alternate contact of relay 34 to ground. The individual signal-control conductor A30 is thereupon grounded through 75 the outer right-hand alternate contact of relay 32. The common start conductor X is also grounded at this time in the same manner as previously described.

The grounding of these two conductors 80 causes the common impulse transmitting apparatus at office W to function in a manner similar to that previously described when the individual signal-control conductors A10 and A20 were grounded at the same time 85 as the start conductor X. However, the third pair of contacts on the selector switch SS is assigned to the jack 30 and the individual signal control conductor A30 is connected to one of said contacts. Therefore, a different combination of impulses is sent over the common signaling path to office X since it is desired to select a different receiving conductor thereat. The character of the impulses sent is such that the common receiving apparatus at the office X selects the signal-receiving conductor E3 90 and sends over such conductor an impulse of negative polarity through the left-hand winding of signal-receiving relay 432 to ground. As in the previous cases, the common sending apparatus at station W, upon completing the transmission of the impulses, connects battery to the conductor B30 to cause the operation of relay 35 which opens 95 the ground connection for the conductors A30 and X. Relay 35 is locked as in the previous cases. After the receipt of the impulses at the station X, the receiving apparatus thereat restores to normal as in the 100

previous instances. Relay 432 in operating completes a locking circuit for itself which extends from battery through the winding of relay 419 and the right-hand winding and middle contact of relay 432 to ground. The closure of the left-hand alternate contact of relay 419, which operates over the circuit just traced, connects ground to the conductor R leading to the motor magnet MM6 and starts such motor magnet operating to advance the brushes of the line switch LS1 step by step. From this point the operation is the same as described previously until the brushes of the switch LS1 are stopped by the ground on conductor P2. This occurs upon the operation of relay 426 which opens the normal contact thereof to open the conductor R so that the motor magnet MM6 ceases its operation and the various brushes controlled thereby remain in their attained position until such motor magnet is again called into service in connection with another call. The closure of the left-hand alternate contact of relay 426 completes the filament circuit of the repeater of amplifier set R 428, and the ground connected through the right-hand alternate contact of relay 426 causes the operation of relay 409 for the purpose of transferring the talking conductors of the trunk line L1, extending from the office W to the line conductors leading through the brush arms 605 and 606 of the line switch LS1, instead of to the tip and ring contacts of the plug 407. The closure of the contact of relay 607 completes a circuit as before, through the windings and contacts of motor magnets MM7 and MM8 in parallel. The motor magnets start operating to advance the various associated brush arms step by step over their respective banks of contacts until the arm 608 finds an idle grounded test lead 609 leading to a trunk circuit extending from the office X to the office Y. Assuming that this is the trunk circuit L1 extending between such offices, relay 425 operates over a circuit extending from battery through the left-hand winding of relay 425, the conductor 429, the brush arm 608, the test conductor to 609, the left-hand normal contact of relay 711 and the left-hand contact of relay 719 to ground. The opening of the right-hand normal contact of relay 425 opens the circuit for maintaining relay 607, which in releasing, opens the circuits for motor magnets MM7 and MM8 so that the brushes of the line switches LS2 and LS3 are maintained in their attained position until employed in connection with the extension of another call. Relay 425 in operating locks as before described. The opening of the left-hand normal contact of relay 425 removes the ground connection from the conductor P2. The closure of the left-hand alternate contact of relay 425 connects battery to a circuit including the winding of marginal relay 414 and the conductor 430. At this time, the talking conductors of the trunk line L1, terminating at office X, are connected to the talking conductors of the trunk line extending from the office X to the office Y, through the brush arms 605 and 606 of line switch LS1, and 619 and 620 of line switch LS3. The proper network or artificial line 737 for balancing the trunk line leading from the office X to the office Y, is also connected with the repeater 428 through the brush arms 617 and 618 of line switch LS3, and the brush arms 603 and 604 of line switch LS1. The proper network for the trunk line L1 extending from the office W to the office X, being permanently connected with the repeater 428, the lines are now properly balanced and the repeater is rendered effective for the transmission of talking currents. The brush arm 616 of line switch LS3 at this time is in engagement with the contact connected to the sleeve conductor 739, so that relay 721 immediately operates over a circuit extending from battery through the left-hand alternate contact of relay 425, the winding of marginal relay 414, the conductor 430, the brush arm 602 of line switch LS1, and the third contact engaged thereby, the brush arm 616, and the third contact engaged thereby, the sleeve conductor 739, the winding of relay 721, the right-hand normal contact thereof, and the right-hand contact of relay 719 to ground. Relay 721, in operating, locks in the same manner that relay 711 locked and thereby effects the energization of relay 719 which, in opening its left-hand contact, removes the ground connection from the testing leads 609, 621 and 622, while the opening of the right-hand contact thereof removes the ground from the energizing circuits of relays 711 and 731 to prevent their becoming energized if selected. The removal of the ground from the testing leads as mentioned, prevents the selection of the trunk L1 during the continuance of this connection. The closure of the right-hand alternate contact of relay 721 causes the operation of relay 716 over an obvious circuit, thereby connecting the talking strands of the trunk line L1 leading from the office X to the office Y and the tip and ring contacts of the jack 720, and disconnecting such conductors from the contacts of jack 710. The closure of the middle alternate contact of relay 721 causes the operation of relays 722 and 723. The closure of the lower right-hand alternate contact of relay 721 connects ground to the inner left-hand armature of relay 724 to prepare a locking circuit therefor. The operation of relay 723 causes the operation of relay 724 over a circuit extending from battery through the right-hand alternate contact of relay 723, the

winding of relay 724 and the normal contact of relay 734 to ground. Relay 724, in operating, locks through its inner left hand contact. Relay 724, in operating, causes the 5 operation of relay 734 over an obvious circuit, the latter relay also locking over an obvious circuit. The operation of relay 734 also causes the locking of relays 722 and 723. The individual signal control conductor A20 10 is thereupon grounded through the outer right-hand alternate contact of relay 722. Simultaneously, the common start conductor X2 is grounded through the inner left hand normal contact of relay 735.

15 The grounding of these two conductors causes the association of the common sending apparatus at the office X with the trunk line L1 leading to the office Y in a manner similar to that described in connection with the 20 tracing of the progress of the call from the office W to the office Y. However, due to the fact that the individual control conductor A20 is grounded instead of the conductor A10, the combination of impulses transmitted over the common signaling path P 25 to the common receiving apparatus at the office Y, is of a different character as compared with that transmitted in the previous case. However, the receipt of these impulses at the office Y causes the selection of conductor E2 thereat instead of E1, and the transmission over such conductor of an impulse of negative polarity. This impulse causes the operation of relay 824 by flowing 30 through its left-hand winding, such relay immediately locking over a circuit extending from battery through the winding of relay 819 and the right-hand winding and middle alternate contact of relay 824 to ground.

35 After the transmission of the impulses by the common sending apparatus at the office X, the conductor B20 is connected to battery to cause the operation of relay 735. 40 Relay 735, in operating, locks over an obvious circuit and opens the ground connection to conductors X2 and A20.

The energization of relay 824 initiates an 45 operation which is similar in every respect to that described in connection with the through call from office W to the line T terminating at office Y. Reference is therefore made to that portion of the foregoing description beginning with the operation 50 of relay 424 and consequent grounding of conductor P' and ending with the signaling of the operator at the terminating office, which in the present instance is the office Z.

55 In following this description it will be 60 found that where similar elements are not designated by exactly the same reference characters, the references are the same with the exception of the hundreds digit or are primed. Briefly, it will be understood that 65 the operation of relay 824 starts the oper-

ation of the line switches in Figure 9 which thereupon select an idle trunk leading to office Z. The sending and receiving apparatus at the latter office then functions to cause the illumination of the guard or line 70 lamp 1105 to indicate to the operator that a call is awaiting attention on trunk L1. It is to be noted that in the operation of the circuits in Figure 9, battery is connected through the marginal relay 814 to the conductor 75 1028 which results in the energization of relay 1011.

The connection of the toll switching trunk circuit Q at the office Z with the trunk line circuit T and of the trunk line L1 with the circuit Q.

The operator at office Z, upon ascertaining the number of the desired line from the operator at office W communicates with the toll switching trunk operator at the office Z, before whom the telephone line T terminates. An order wire (not shown) of the usual type may be used for this purpose in the ordinary manner. The toll switching 85 operator designates the toll switching trunk circuit Q as the one which should be used for extending the connection. Immediately upon assigning the trunk circuit Q for this purpose, the toll switching trunk operator thereupon inserts plug 500 into jack 501 of the line T with the result previously 90 described.

The operator at office Z, upon receiving the assignment of a trunk from the toll 100 switching operator, inserts the plug 1107 into the jack 509 of the trunk circuit Q. Relays 1106 and 1108 operate in the same manner as described in connection with relays 806 and 808 when the call was being 105 extended to the office Y. Lamp 1105 is also extinguished in a similar manner.

The supervisory relay 1104 of the trunk line L1, extending from office Y to office Z and the relay 508 in the toll switching trunk 110 circuit Q, operate in a manner similar to that described in connection with the operation of relay 508 and relay 804. In response to the operation of relay 508, the lamp 506 is extinguished. Supervisory relay 115 1104, in operating, causes relays 1111, 1112 and 1113 to operate in a manner similar to that described in connection with relays 811, 812 and 813, and as a consequence ground is connected to the individual signal-control 120 conductor A'10 and the common start conductor X4 at the office Z. The grounding of these two leads causes the common sending apparatus at the office Z to become associated with the trunk line L1 and to transmit a 125 series of impulses over the common signaling path P to the office Y in a manner similar to that described in connection with the transmission of the similar signal office Y to office X. Immediately upon transmitting these 130

impulses the conductor B'10 at the office Z is connected to battery to cause the operation of relay 1115 over an obvious circuit which disconnects ground from the conductors A'10 and X4 thereat to effect the same operations previously described. The impulses, upon being received at the outgoing end of office Y, are caused to select the individual signal-receiving conductor E' and 10 to transmit thereover an impulse of negative polarity which, in flowing through the left-hand winding of relay 1027 causes it to operate and to lock over an obvious circuit. The operation of relay 1027 connects the resistance 1026 in a shunt path around the winding of relay 1021, so that the current flowing over the sleeve conductor 1039, through the marginal relay 814, is sufficiently increased to cause the operation of 15 the latter relay. The operation of relay 814 causes the operation of relays 811, 812 and 813 in a similar manner to that described in connection with the operation of relay 411, 412 and 413. Relay 813, in operating, has 20 the same effect as the operation of relay 413 with the result that ground is connected to individual control conductor A'10 and common start conductor X' (Fig. 8) in the manner previously described to transmit a series 25 of impulses over the common signaling path P to the office X. This combination of impulses is the same as that previously mentioned in connection with the extension of the call to the office Y. Upon the transmission 30 of the impulses, the conductor B'10 at office Y is connected to battery with the same result as previously mentioned. Ground is thus disconnected from both of the control conductors and the common sending apparatus 35 is restored to normal. The impulses received at the office X perform the same functions as described in connection with the extension of the call to the office Y, except that due to the operated condition of 40 relay 723, the resistance 726 is placed in parallel relation with the winding of relay 721 instead of the winding of relay 711. However, as before, the marginal relay 414, included in the sleeve conductor 739, is 45 operated due to the increase in current flowing therethrough and thereupon performs the same functions as previously described. Such operations cause the temporary grounding of the signal-control conductor A'10 and the common start conductor X' at 50 the office X, and the transmission of the same combination of impulses over the common sending path P to the office W. As before, upon the transmission of the impulses, an 55 impulse is received through the conductor B and the winding of relay 415, causing its release, to remove the ground from such conductors. The impulses, upon being received at the office W, select the receiving lead E', and current flows through the left-hand 60

winding of relay 27, causing its operation, thereby placing the resistance 26 in parallel relation with the winding of relay 31. Relay 27, upon energizing, locks as in the previous cases. The parallel relation of resistance 26 around the winding of relay 31 permits enough current to flow through the winding of relay 6 in the cord circuit O to cause its operation and the consequent lighting of the supervisory lamp 7 to serve as a ringing signal to the operator at the office W. 70 75

The operator at office W actuates the ringing key.

The operator at office W, observing the so lighted condition of the supervisory lamp 7, is advised that the connection has been established to the telephone line circuit T at the office Z, through the offices X and Y. The ringing key 2 is then actuated which completes a circuit from the source of ringing current through the lower alternate contact of key 2, the ring contacts of plug 1 and jack 30, the lower alternate contact of relay 16 the condenser 18, the winding of relay 17, the upper alternate contact of relay 16, the tip contacts of jack 30 and plug 1, and the upper alternate contact of key 2 to ground. The ringing response relay 17 operates as in the previous cases, to cause the operation of relay 25, both such relays being maintained operated while the ringing key remains operated but release when the key is released. As in the previous instance, the operation of relay 25 opens the locking circuit of and permits the release of relay 35, but no signal is transmitted to the other offices while the ringing current is present upon the line. 90 95 100

The operator at office W releases the ringing key.

When the key 2 is released, relays 17 and 25 release, and common start conductor X and individual signal-control conductor A30 are again grounded in the manner previously described in connection with the insertion of the plug 1 into the jack 30. The grounding of these leads causes the same combinations of impulses to be sent over the common signaling paths P extending between the office W and X, and upon their receipt at office X, the same signal-receiving conductor is selected as before. The last impulse of such current flow operates relay 432 which immediately locks through its right-hand winding and causes the operation and locking of relay 419. The conductor 431 thereupon receives a momentary impulse of current over a circuit which is similar to that traced in connection with the transmission of the ringing signal from the office W to the office Y. Relay 623 operates in response to this impulse and causes the operation of relay 715, followed by the operation of re- 110 115 120 125 130 135

lays 725 and 714 to temporarily ground the signal-control conductor A20 and the common start conductor X2 to cause to be transmitted a similar combination of impulses as in the previous instance to the office Y. These impulses differ somewhat from the impulses transmitted when the line circuit at the office Y was desired so that upon the arrival at the office Y, the conductor E2 is selected and as a consequence relay 824 is operated and locked, causing the operation of relay 819 thereafter. As in the previous cases, the common signal-transmitting and receiving arrangements are disconnected from the line circuit extending between office X and Y and are rendered available for use with other line circuits. At the office Y, due to the operation of relay 824, the conductor 831 receives a momentary impulse of current, which causes the operation of relay 923, and relay 923 in operating, causes lays 1014, 1015 and 1025 to function in the same manner as just described in connection with relays 714, 715 and 725. These relays, in functioning, cause the common start conductor X4 and the individual signal control conductor A10 to become grounded simultaneously. The grounding of these conductors causes the transmission of the same combination of impulses as was transmitted from the office Y to the office Z in response to the insertion of the plug 1 into jack 30. These impulses, upon receipt at the office Z select the signal-receiving conductor E thereat and inasmuch as the polarity of the last impulse is the same as that previously transmitted, it has no effect upon relay 1100; but due to the deenergized condition of relay 1102 and the relay 1101 is operated so that slow relay 1121 is operated over an obvious circuit, causing the subsequent operation of slow relay 1122. As a result of these operations, relay 1110 is operated for a predetermined period which depends upon the rapidity with which the various mentioned apparatus operate and release. While relay 1110 remains operated, ringing current is projected over the trunk line L1 to the switching circuit Q where the same action takes place as previously described to ring the subscriber's bell.

The called subscriber removes the receiver from the switchhook.

The subscriber at the station on the line circuit T terminating at office Z, in response to the signal given by the bell thereat, removes the receiver from the switchhook which causes the apparatus of trunk circuit Q to function as described in connection with the previous instances, and to further cause the deenergization of relay 1104. Relay 1104, in deenergizing, causes the operation of relays at office Z similar to those controlled by relay 804. Said relays, in-

cluding relay 1116, function in the same manner as the similar relays at office Y, to cause the grounding of the signal control conductor C'10 and the common start conductor X4 to cause the common sending apparatus to transmit the same series of impulses to the office Y as were transmitted from office Y when the call terminated thereat. The impulses received at the office Y select the signal-receiving conductor E' as in the other case and due to the difference of polarity of the last impulse, relay 1027 is differentialized, removing the resistance 1026 from its parallel relation with the winding of relay 1021. Thus the current flowing through the marginal relay 814 is decreased sufficiently so that such relay deenergizes and in deenergizing, causes the various relays at office Y to function in the same manner as described in connection with the deenergization of relay 804 upon the answer of the called party at the office Y. As a consequence, a similar combination of impulses is repeated and transmitted from the office Y to the office X, being received thereat over the signaling conductor E' and causing relay 727 to become differentialized. Upon the differentialization of relay 727 the resistance 726 is removed from the shunt relation around the winding of relay 721, thus decreasing the current flowing through the marginal relay 414 sufficiently to cause its deenergization. The deenergization of relay 414, as previously described, causes the functioning of various relays at office X in a manner similar to that described in connection with deenergization of relay 404 upon the answer of the called party at office X. The common sending apparatus is then brought into service and caused to transmit the same set of impulses from the office X to the office W, where they are received by the receiving relay 27, to cause its differentialization, thereby removing resistance 26 from shunt relation with the winding of relay 31. Relay 6 then receives insufficient current to maintain it operated and upon its release, lamp 7 extinguishes to indicate that the called party at office Z has answered the call.

The subscriber restores the receiver to the switchhook.

At the conclusion of the conversation, the subscriber at the station on the line circuit T terminating at office Z restores the receiver to the switchhook, causing certain apparatus of the toll switching trunk Q to function as previously mentioned, and upon the functioning of such apparatus supervisory relay 1104 is again energized and causes the apparatus at the various offices of the system to function in a manner similar to that described in connection with the insertion of the plug 1107 into the jack 509

of the toll switching trunk circuit Q. It is not thought necessary to describe this in detail except to state that due to the replacing of resistance 26 in shunting relation with the winding of relay 31, marginal relay 6 of the cord circuit O again operates to cause the lighting of the lamp 7 thus indicating to the operator at office W that the subscriber at the station on the line circuit T terminating at office Z has signalled for a disconnection.

The operator at office W disconnects the toll cord circuit O from the trunk line L1.

Upon observing the lighted condition of the supervisory lamp 7, the operator at office W withdraws the plug 1 from the jack 30, causing the release of relays 6, 31, 19 and 16. The release of relays 6, 19 and 16 performs the same functions as previously described in connection with the other cases. The release of relay 31 in opening its lower right-hand alternate contact, causes the release of relay 24, which in releasing connects ground to the common start conductor X over the circuit previously described therefor, and the individual signal-control conductor C30 is also grounded over a path extending from the left-hand normal contact of relay 24, the outer left-hand alternate contact of relay 34, and the left-hand contact of relay 33. The grounding of these two conductors again causes the common signaling apparatus at the office W to transmit the combination of impulses over the common signaling path P to the office X, but due to the fact that the second contact of the pair of contacts assigned to the jack 30 is now grounded, the character of the selecting impulses is varied, so that an impulse of positive polarity is transmitted over the selected signal-receiving conductor E3 at the office X, which causes relay 432 to become differentialized and released. Upon the sending of the combination of impulses, battery is connected to the conductor D30, which flows through the right-hand winding of differential relay 34, causing such relay to release, and in opening its inner left-hand alternate contact removes ground from the maintaining circuits of relays 33 and 32, allowing such relays to release and restoring the apparatus associated with the trunk line L1 at the office W to normal. Relay 419 is also released upon the receipt of the impulses, and the opening of the inner right-hand alternate contact of relay 432 removes ground from the locking circuit of relay 425 so that such relay releases to remove the battery connection from the circuit including the marginal relay 414, the conductor 430 and the sleeve conductor 739. The repeater set R428 is restored to its normal state by the opening of the left-hand alternate contact of relay 426 which releases upon the

release of relay 432. Relay 721 releases due to the removal of battery on the sleeve conductor 739 and in releasing, causes the release of relays 719 and 716 which perform their usual functions similar to those of relays 19 and 16. The opening of the lower right-hand alternate contact of relay 721 causes the release of relay 724, which cooperates with relays 734, 722 and 723 in a manner similar to that described in connection with relays 24, 34, 32 and 33 at the office W. However, due to the fact that relays 722 and 723 are associated with the jack 720, the individual signal-control conductor C20 is grounded simultaneously with the start conductor X2 instead of the corresponding individual signal-control conductor C30. All of these relays function in exactly the same manner as those mentioned, and the grounding of the conductors cause the similar series of impulses to be transmitted from the office X to the office Y as described in connection with the transmission of the impulses from the office W to the office X. The receipt of these impulses at the office Y causes relays 824, 825 and 814 to function in a manner similar to that described for relays 432, 425 and 414 at the office X. In this case, the marginal relay 814 is included in a circuit with the sleeve conductor 1038 and relay 1011 at the office Y, so that relay 1011 releases and in releasing causes relays 1024, 1034, 1012 and 1013 to function as previously described in connection with similar relays, at the office X. Relays 1019 and 1016 also release as described in connection with relays 16 and 19 at the office W and perform similar functions. However, due to the fact that relay 1013 is employed in this instance, the individual signal-control conductor C10 is grounded simultaneously with the common start conductor X4, so that the common sending and receiving apparatus is again called into service to transmit the same set of impulses over the common sending path P between offices Y and Z, as was transmitted between offices X and Y. However, these impulses, upon being received at office Z, select the receiving conductor E and due to the character of the current flowing thereover, cause relay 1100 to differentialize and release, opening the bridge including the supervisory relay 1104 across the outward end of the trunk line L1, and causing the illumination of lamp 1105 at the terminating operator's position at the office Z to indicate that the operator at office W has disconnected the line.

As in the case of the extension of the call to the station at office Y, the opening of the bridge including relay 1104 causes the apparatus in the trunk circuit Q to function so as to illuminate the lamp 506 to serve as a disconnect signal to the toll switching trunk operator. Both terminating and trunk

switching operators at the office Z may thereupon remove the plugs of the trunk line L1 and the trunk circuit Q from the connecting jacks, thereby restoring all apparatus to normal.

The subscriber recalls the operator at the office W.

Should the subscriber at the station on the 10 trunk line circuit T desire to recall the operator at the office W before the connection has been removed, this may be accomplished by repeatedly opening and closing the switchhook contacts at the station. Since 15 the apparatus at office Z associated with the trunk line L1 is similar in all respects to that associated with the trunk line L1, terminating at office Y, these operations of the 20 switchhook cause the similar apparatus to function in the same manner at office Z as the operations would at the office Y. Therefore, while the subscriber is rapidly operating the switchhook, a sufficient number of 25 impulses are transmitted from the office Z to the office Y and from the office Y to the office X and thence to the office W in a manner similar to that described in connection 30 with the line circuit at office Y. These impulses, upon being received at the office W, cause the apparatus to function thereat in exactly the same manner as described in connection with the extension of the call to the office Y, to cause the supervisory lamp 7 to 35 flash at a constant rate, as determined by the interrupter 36, to serve as a recall signal.

If, after repeatedly opening and closing the switchhook, the subscriber leaves the receiver on the switchhook, the apparatus at office Z functions in the same manner as the 40 similar apparatus at office Y functioned in connection with the similar act on the part of the subscriber whose line terminated at the office Y and was connected with the trunk line L1. Therefore, suitable impulses 45 are transmitted in exactly the same manner as previously mentioned, from the office Y to the office X and thence to the office W as were transmitted in the previous case to cause the steady illumination of the lamp 7 50 at the latter office to serve as a disconnect signal.

However, in case the subscriber, after performing the act of recall, desires to leave the receiver off the switchhook, the apparatus at 55 the office Z will function in the manner described for the similar apparatus at the office Y in connection with the similar act of the subscriber whose line terminated at office Y and connected with the trunk line L1 there- 60 at. Therefore, the impulses transmitted from office Y to the office X and from the office X to the office W will be the same as those transmitted in the previous case, and will in a like manner cause the permanent

extinguishment of the lamp 7 to indicate 65 that the subscriber whose line terminates at the office Z desires to reestablish the connection.

What is claimed is:

1. In a telephone system, an originating 70 office, a plurality of intermediate offices, a terminating office, a plurality of trunk circuits interconnecting said offices, a signaling path common to said trunk circuits, means controlled at the originating office for sending code impulses over said signaling path, means at each intermediate office for receiving said impulses, and means controlled thereby for connecting each intermediate office to a succeeding intermediate office and 75 to said terminating office.

2. In a telephone system, an originating 80 office, a plurality of intermediate offices, a terminating office, a plurality of trunk circuits interconnecting said offices, a signaling 85 path common to said trunk circuits, means controlled at the originating office for sending code impulses over said signaling path, means at each intermediate office for receiving said impulses, means controlled thereby 90 for connecting each intermediate office to a succeeding intermediate office and to said terminating office, and repeater sets arranged for connection with the trunk circuits joining said originating, intermediate 95 and terminating offices.

3. In a telephone system, an originating 100 office, a plurality of intermediate offices, a terminating office, a plurality of trunk circuits interconnecting said offices, a signaling 105 path common to said trunk circuits, means controlled at the originating office for sending code impulses over said signaling path, means at each intermediate office for receiving said impulses, means controlled thereby 110 for connecting each intermediate office to a succeeding intermediate office and to said terminating office, repeater sets, and means determined by the code impulses transmitted over said signaling path for connecting said repeater sets to the trunk circuits interconnecting said originating, intermediate and terminating offices.

4. In a telephone system, an originating 115 office, a plurality of intermediate offices, a terminating office, a plurality of trunk circuits interconnecting said offices, a signaling 120 path common to said trunk circuits, means controlled at the originating office for sending code impulses over said signaling path, means at each intermediate office for receiving said impulses, means controlled thereby 125 for connecting each intermediate office to a succeeding intermediate office and to said terminating office, a signaling device at the terminating office, and means responsive to code impulses transmitted from an intermediate office to the terminating

office for operating said signaling device.

5. In a telephone system, an originating office, a plurality of intermediate offices, a terminating office, a plurality of trunk circuits interconnecting said offices, a signaling path common to said trunk circuits, means for sending code impulses over said signaling path, means at said intermediate offices for receiving said impulses and means controlled thereby at each intermediate office for automatically selecting an idle trunk circuit leading to a succeeding intermediate office and to the terminating office, and to connect said trunk circuit with the trunk circuit leading from the originating office.

6. In a telephone system, an originating office, an intermediate office, a terminating office, a signaling device at the latter office, a plurality of trunk circuits interconnecting said offices, a signaling path common to said trunk circuits, a plurality of connecting terminals for each trunk circuit at the originating office, a plurality of connecting terminals for each trunk circuit at the intermediate offices, the terminals at said originating and intermediate offices being correspondingly arranged, a link circuit at the originating office for connection with the terminals thereat, means responsive to the connection of said link circuit with one of the connecting terminals of the selected trunk circuit at said originating office to transmit code impulses over said signaling path to said intermediate office to identify a terminal thereat other than the one which corresponds to the selected terminal at the originating office, and means at the terminating office responsive to the identification of the terminal at said intermediate office for operating said signaling device.

7. In a telephone system, an originating office, a plurality of intermediate offices, a terminating office, a plurality of trunk circuits interconnecting said offices, a signaling path common to said trunk circuits, a plurality of connecting terminals for each trunk circuit at said originating office, a plurality of connecting terminals for each trunk circuit at each intermediate office, the terminals at the originating and intermediate offices being correspondingly arranged, means controlled by the selection of a connecting terminal at the originating office for transmitting code impulses to the various intermediate offices whereby to identify connecting terminals at said intermediate offices other than the terminals thereat which correspond to a selected terminal at the originating office, means at the intermediate offices for receiving said impulses and means controlled thereby to connect a trunk circuit leading from the originating office to a trunk circuit extending to the terminating office.

8. In a telephone system, an originating office, a plurality of intermediate offices, a terminating office, a signaling device at the latter office, a plurality of trunk circuits interconnecting said offices, a signaling path common to said trunk circuit, a plurality of connecting terminals for each trunk circuit at the originating office, a plurality of connecting terminals for each trunk circuit at each of the intermediate offices, the terminals at said originating and intermediate offices being correspondingly arranged, a link circuit at the originating office for connection with the terminals thereat, means responsive to the connection of said link circuit with one of the connecting terminals of a selected trunk circuit at said originating office to transmit code impulses over said signaling path to an adjacent intermediate office to identify a terminal thereat other than one which corresponds to the selected terminal at the originating office, means responsive to the identification of the terminal at said adjacent intermediate office to transmit code impulses to another intermediate office to identify a terminal thereat other than ones which correspond to the selected terminal at said originating office and the identified terminal at said adjacent intermediate office, and means at the terminating office responsive to the identification of the terminal at said other intermediate office for operating said signaling device.

9. In a signaling system, originating and terminating offices, a plurality of intermediate offices, a trunk circuit interconnecting said offices and terminating at said originating office in terminals individual to said other offices, means responsive to the seizure of said trunk circuit through terminals individual to the terminating office for transmitting code impulses from said originating office through said plurality of intermediate offices to said terminating office, and means controlled by said code impulses for identifying at said terminating office the communication channel of which said trunk forms a part.

10. In a signaling system, originating and terminating offices, a plurality of intermediate offices, a plurality of trunk circuits interconnecting said offices, each terminating at the originating office in terminals individual to said other offices, a signaling path common to said trunk circuit, means responsive to the seizure of one of said trunk circuits through the terminals corresponding to said terminating office for transmitting code impulses from said originating office through said plurality of intermediate offices to said terminating office over said common signaling path, and means controlled by said code impulses for identify-

ing at said terminating office the communication channel of which said seized trunk forms a part.

11. In a signaling system, originating and terminating offices, a plurality of intermediate offices, a trunk circuit interconnecting said offices and terminating at said originating office in terminals individual to said other offices, means responsive to the seizure 10 of said trunk circuit through terminals individual to said terminating office for transmitting code impulses from said originating office through said plurality of intermediate offices to said terminating office, and 15 repeater sets for said trunk circuit rendered active by said code impulses.

12. In a signaling system, originating and terminating offices, a plurality of intermediate offices, a trunk circuit, means for transmitting 20 code impulses from said originating office over a path independent of said trunk to successively connect the same to each of said plurality of intermediate offices and to said terminating office, and means 25 controlled by said code impulses for identifying at said terminating office the communication channel of which said trunk forms a part.

13. In a signaling system, a plurality of 30 offices, trunk circuits interconnecting said offices, means responsive to the seizure of a trunk circuit at one office for transmitting code impulses therefrom, means at another office responsive to said code impulses for connecting said trunk circuit to a different trunk circuit, means thereupon 35 operable to transmit code impulses from said other office, and means at a third office responsive to the latter code impulses for 40 identifying the last named trunk circuit.

14. In a signaling system, a plurality of offices, trunk circuits interconnecting said offices, means responsive to the seizure of a trunk circuit at one office for transmitting 45 code impulses therefrom, selective switches at another office responsive to said code impulses for connecting said trunk circuit to a different trunk circuit, means thereupon operable to transmit code impulses from said 50 other office, and means at a third office responsive to the latter code impulses for identifying the last named trunk circuit.

15. In a signaling system, a plurality of offices, trunk circuits interconnecting said 55 offices, means responsive to the seizure of a trunk circuit at one office for transmitting code impulses therefrom, means at the other offices responsive to the transmission of said code impulses for connecting said trunk circuit to different trunk circuits extending between said other offices, a terminating office, and means therefor identifying the last trunk circuit to which the first trunk circuit is connected.

16. In a signaling system, a plurality of

offices, trunk circuits interconnecting said offices, a signaling path common to said trunk circuits, means responsive to the seizure of a trunk circuit at one office for transmitting code impulses over said signaling path, means at another office responsive to said code impulses for connecting said trunk circuit to a different trunk circuit, means thereupon operable to transmit code impulses over said path from said other office, and means at a third office responsive to the latter code impulses for identifying the last named trunk circuit. 70 75

17. In a switching system, a plurality of offices, a plurality of trunk circuits interconnecting said offices, a signaling path common to said trunk circuits and means responsive to the seizure of one of said trunk circuits for controlling over the signaling path the establishment of a connection between two 80 85 of said offices over different trunk circuits.

18. In a signaling system, a plurality of offices, a plurality of trunk circuits interconnecting said offices, and means including start-stop distributors responsive to the initiation of a call at one of said offices for establishing a connection to another office over more than one of said trunk circuits. 90

19. In a signaling system, a plurality of offices, a plurality of trunk circuits interconnecting said offices, a plurality of correspondingly arranged connecting terminals for each trunk circuit at said offices, and means responsive to a connection to a connecting terminal of one of said trunk circuits at one of said offices to identify at another office a terminal thereat other than the one which corresponds to the first named terminal. 95 100

20. In a signaling system, a plurality of offices, a plurality of trunk circuits interconnecting said offices, a plurality of correspondingly arranged connecting terminals for each trunk circuit at said offices, and means responsive to a connection to a connecting terminal of one of said trunk circuits at one of said offices to identify at another office a terminal thereat of said trunk circuit other than the one which corresponds to the first named terminal. 105 110 115

21. In a signaling system, a plurality of offices, a plurality of trunk circuits interconnecting said offices, a plurality of connecting terminals for each trunk circuit at each of said offices, the connecting terminals of each trunk circuit being correspondingly arranged with respect to connecting terminals of the same trunk circuit and also of other trunk circuits, and means responsive to a connection to a terminal of a trunk circuit at one of said offices to identify at another office a connecting terminal of a different trunk circuit, the latter terminal being other than the one at said other office which 120 125 130 trunk circuit, and means responsive to con-

- corresponds to the first named connecting terminal.
22. In a switching system, a plurality of offices, a plurality of trunk circuits interconnecting said offices, a signaling path common to said trunk circuits and extending between the various offices, and means controlled over said signaling path for establishing a connection between two of said offices over different trunk circuits.
23. In a signaling system, a plurality of offices, trunk circuits interconnecting said offices, a repeater set for each trunk circuit, a signaling path common to said trunk circuits, and means controlled over said signaling path for selecting an idle trunk circuit at one of said offices and for building up the repeater set associated with the selected trunk circuit.
24. In a signaling system, a plurality of offices, trunk circuits interconnecting said offices, a repeater, and a balancing network for each of said trunk circuits, and means controlled from one office for selecting an idle trunk circuit at another office and for associating the balancing network of the selected trunk circuit with the repeater therefor.
25. In a signaling system, a plurality of offices, trunk circuits interconnecting said offices, a signaling path common to said trunk circuits, and a balancing network, a repeater for each trunk circuit, and means controlled from one office over said signaling path for selecting an idle trunk circuit at another office, and for associating the balancing network of the selected trunk circuit with the repeater therefor.
26. In a signaling system, a plurality of offices, trunk circuits interconnecting said offices, a repeater set, and means controlled from one office for selecting an idle trunk circuit at another office and for building up the repeater set for use with said selected trunk circuit.
27. In a signaling system, a plurality of offices, a trunk circuit interconnecting said offices, means responsive to the seizure of said trunk circuit at one office for transmitting impulses from said office through all of the other offices but one, and means controlled by said impulses for identifying said trunk circuit at said one office.
28. In a signaling system, an originating office, an intermediate office, a terminating office, a trunk circuit interconnecting the originating and intermediate offices, a trunk circuit interconnecting the intermediate and terminating offices, a signaling path independent of said trunk circuits, means controlled at the originating office for transmitting impulses over said signaling path, means at the intermediate office responsive to the impulses to interconnect said trunk circuits, means for transmitting impulses over said path to the terminating office, a signaling device at the terminating office, and means responsive to the last named impulses for operating said signaling device.
29. In a signaling system, an originating office, an intermediate office, a terminating office, a plurality of trunk circuits interconnecting the originating and intermediate offices, a plurality of trunk circuits interconnecting the intermediate and terminating offices, a signaling path common to said trunk circuits, a signaling device associated with each trunk circuit at the terminating office, means for transmitting impulses from said originating office over said signaling path, means at the intermediate office for receiving said impulses, means controlled thereby to connect a selected trunk circuit with a trunk circuit leading to the terminating office and to cause the transmission of impulses over said signaling path to said terminating office, means at the terminating office for receiving the impulses, and means controlled thereby for operating the signaling device associated with the last named trunk circuit.
30. In a signaling system, an originating office, an intermediate office, a terminating office, a plurality of trunk circuits, interconnecting the originating and intermediate offices, a plurality of trunk circuits interconnecting the intermediate and terminating offices, a signaling path common to said trunk circuits, means controlled at the originating office for sending impulses over said path, means at the intermediate office for receiving the impulses, and means controlled thereby for automatically finding an idle trunk circuit leading to the terminating office, and to automatically connect such trunk circuit with a selected trunk circuit extending from the originating office.
31. In a signaling system, a plurality of offices, a trunk circuit extending from one office and terminating at one of the other offices, a plurality of terminals for each trunk circuit, a signaling path for said offices independent of said trunk circuit, a link circuit at each office, means responsive to the connection of the link circuit with one of the terminals of the trunk circuit at one office to associate the trunk circuit with said signaling path, means responsive to such association to transmit impulses over such signaling path to an adjacent office, means responsive to said impulses to automatically interconnect the selected trunk circuit from the first mentioned office with a trunk circuit extending from the second mentioned office to a third office, a signal at the third office associated with the last mentioned connection of the second mentioned office to the third office for operating said signal.

32. In a signaling system, an originating office, an intermediate office, a terminating office, a plurality of trunk circuits interconnecting the originating and intermediate offices, a plurality of trunk circuits interconnecting the intermediate and terminating offices, a signaling path common to said trunk circuits, means controlled at the originating office for transmitting impulses over said signaling path, means at the intermediate office for receiving the impulses, means controlled thereby to connect a trunk circuit leading from the originating office to a trunk circuit extending to the terminating office, and a repeater set arranged for connection with the trunk circuits interconnecting said originating and terminating offices.

33. In a signaling system, an originating office, an intermediate office, a terminating office, a plurality of trunk circuits interconnecting said offices, a signaling path common to said trunk circuits, means controlled at the originating office for transmitting impulses over said signaling path, means at the intermediate office for receiving the impulses, means controlled thereby to connect a trunk circuit leading from the originating office to a trunk circuit extending to the terminating office, a repeater set, and means determined by the impulses transmitted over said signaling path for connecting said repeater set to the trunks interconnecting said originating and terminating offices.

34. The method which comprises selecting a trunk interconnecting two offices, transmitting a code of impulses over a path independent of said trunk, receiving said impulses at one of said offices and, in response thereto, selecting a trunk extending to a third office.

35. The method which comprises selecting a trunk interconnecting two offices, transmitting a code of impulses over a path independent of said trunk, receiving said impulses at one of said offices, in response thereto, selecting a trunk extending to a third office and identifying said last mentioned trunk at said third office.

36. The method which comprises selecting a trunk interconnecting two offices, transmitting a code of impulses over a path independent of said trunk, receiving said impulses at one of said offices, selecting a trunk extending to a third office and interconnecting said trunks.

37. The method which comprises selecting a trunk interconnecting two offices, transmitting a code of impulses over a path independent of said trunk, receiving said impulses at one of said offices, selecting a trunk leading to a third office, interconnecting said trunks, transmitting a code of im-

pulses from said receiving office over a path independent of said trunks, receiving said impulses at said third office and translating said last mentioned received impulses into a signal.

38. The method which comprises selecting a trunk interconnecting two offices, transmitting a code of impulses over a path independent of said trunk, receiving said impulses at one of said offices and in response thereto connecting said trunk with a trunk extending to a third office.

39. The method of building a sectionalized trunk which comprises transmitting a code of impulses over a path independent of the trunk and in response thereto selecting and interconnecting the trunk sections.

40. In a signaling system, a plurality of offices, a trunk circuit interconnecting two offices, trunk circuits extending from one of said offices to a third office, an independent path connecting said offices, means for transmitting a code of impulses over said path, means for receiving said impulses at one of said offices and means responsive thereto for selecting a trunk extending to a third office.

41. In a signaling system, a plurality of offices, a trunk circuit interconnecting two offices, trunk circuits extending from one of said offices to a third office, an independent path connecting said offices, means for transmitting a code of impulses over said path, means for receiving said impulses at one of said offices and means responsive thereto for selecting a trunk extending to the third office and identifying said last mentioned trunk at said third office.

42. In a signaling system, a plurality of offices, a trunk circuit interconnecting two offices, trunk circuits extending from one of said offices to a third office, an independent path connecting said offices, means for transmitting a code of impulses over said path, means for receiving said impulses at one of said offices and means responsive thereto for selecting a trunk extending to the third office and for interconnecting said last mentioned trunk and the trunk extending between the first mentioned two offices.

43. In a signaling system, an originating office, an intermediate office, a terminating office, a trunk circuit interconnecting the originating and intermediate offices, trunk circuit interconnecting the intermediate and terminating offices, a terminal associated with the trunk circuit at the originating office assigned specially for connections to be made from the originating office through the intermediate office to the terminating office, an independent path connecting the originating and intermediate offices, means connected with said terminal for transmitting a code of impulses

over said path, means for receiving said impulses at the intermediate office and means responsive thereto for selecting a trunk extending to the third office and for interconnecting said last mentioned trunk and the trunk from the originating office.

In witness whereof, I hereunto subscribe my name this 20th day of December A. D., 1920.

HUGH D. MACPHERSON.
